ABSTRACT

A modular portable storage container system includes container sections, each having a frame. A latch mechanism retains the frames against an infrastructure substrate. The latch mechanism has: a spring latch, latch receiver, and retaining hook. The container sections are movable between unlatched and latched positions. When unlatched, the container sections are movable relative to the substrate and when latched the frames of the container sections are retained in contact with mounting points of the substrate via the latch mechanism. The spring latch and the latch engage one another when the container sections are in the latched position, and the retaining hook engages with the frame to rotatably retain the frame. The spring latch and retaining hook include mounting flanges that are selectively slidably and fixedly mountable to mounting points of the infrastructure substrate in one or more positions defined by a size of the container sections.

MODULAR PORTABLE STORAGE CONTAINER SYSTEM

CROSS-REFERENCE TO RELATED APPLICATIONS

The present application is a continuation-in-part of U.S. continuation-in-part application Ser. No. 18/047,832 filed Oct. 19, 2022, which is a continuation-in-part of U.S. continuation-in-part application Ser. No. 17/717,604 filed Apr. 11, 2022, which in turn is a continuation-in-part of U.S. application Ser. No. 17/410,412 filed on Aug. 24, 2021. The disclosures of the above applications are incorporated herein by reference in their entirety.

INTRODUCTION

The present disclosure relates to containers, and more specifically to containers for storage and transport of a wide variety of objects in various applications.

Vehicle users often use cargo compartments within their vehicles to move cargo, packages, and objects more generally, from place to place. Typically, a vehicle user will manually load a cargo compartment within their vehicle with those cargo, packages, and other objects. In some instances, mechanical or automated devices may assist in such loading and/or unloading of the vehicle cargo compartments. While current systems and methods for loading and unloading vehicle cargo compartments certainly continue to work, there is a need in the art for a simplified system that reduces the number of times that a user must interact with the cargo before, during, and after transit to a use or delivery location. Likewise, there is a need in the art for a scalable, high portability storage system that can be safely and securely used in a wide variety of fields of endeavor, including but not limited to private, industrial, and warehouse applications. Further, there is a need in the art for a scalable high-portability storage system that can be manufactured at relatively low cost, with low complexity.

SUMMARY

A modular portable storage container system includes a first container section defining a first partial volume of storage space, and a second container section defining a second partial volume of storage space, each of the container sections having a structural frame. The system further includes a latch mechanism selectively retaining the structural frame of each of the first container section and the second container section against an infrastructure substrate. The latch mechanism has: a spring latch, a latch receiver, and a retaining hook. One of the spring latch and the latch receiver is disposed on mounting points disposed either directly or indirectly on the infrastructure substrate while the other of the spring latch and the latch receiver is disposed on the structural frames of each of the first container section and/or the second container section. The first and second container sections are movable between at least an unlatched position and a latched position. In the unlatched position, the first and second container sections are freely movable relative to the infrastructure substrate and the mounting points and in the latched position the structural frames of each of the first and second container sections are retained in contact with the mounting points of the infrastructure substrate via the latch mechanism. The spring latch and the latch receiver are disposed opposite one another and engage with one another when the first container section and/or the second

container section are in a latched position. The retaining hook engages with an outer vertical portion of the structural frame to partially rotatably retain the structural frame. Each of the spring latch and the retaining hook include mounting flanges that are selectively fixedly mountable to the mounting points of the infrastructure substrate in one or more positions defined by a size of the first container section, or a size of the second container section.

In another aspect of the present disclosure the infrastructure substrate includes at least one of: walls and floors of buildings, walls and floors of vehicles or vehicle cargo compartments; stakes of a stake truck; an interior or exterior wall of a semi or semi tractor trailer; a wall or interior surface of an aircraft or aircraft fuselage; a wall or interior surface of a watercraft; a wall or interior surface of a train or train car; interior walls, doors, and floors of shipping containers; interior walls, doors, and floors of shipping crates.

In another aspect of the present disclosure the system further includes a mounting track affixed to the infrastructure substrate, the mounting track having one or more of the mounting points, the mounting flanges of the spring latch and the retaining hook being selectively, fixedly mountable to the mounting points.

In another aspect of the present disclosure the system further includes each of the mounting flanges further includes: at least one slide lock movable between at least an engaged position and a disengaged position, the slide lock selectively engageable with the mounting points of the mounting track. When the at least one slide lock is in the disengaged position, the mounting flanges are movable relative to the mounting track. When the at least one slide lock is in the engaged position, the mounting flanges are immovably secured to the mounting track.

In another aspect of the present disclosure the system further includes each of the at least one slide locks further includes: a lock housing fixed to the mounting flanges, lock arms movably disposed within the lock housing, and a lock spring disposed within the lock housing, and between the lock arms. The lock spring biases the lock arms away from each other. The lock arms lockingly engage with the mounting points of the mounting track and immobilize the slide lock relative to the mounting track in the engaged position.

In another aspect of the present disclosure the system further includes each of the at least one slide locks further includes a lock clip, the lock clip having clip arms extending from a clip base to clip detents, the clip arms being substantially parallel to one another, and substantially orthogonal to the clip base, the clip detents, clip base. The slide lock further includes clip arms sized and shaped to surround and lockingly engage with a center post of the mounting flange. The center post of the mounting flange is located between the lock arms.

In another aspect of the present disclosure in the disengaged position, the lock arms are movable towards and away from the center post, and in the engaged position, the lock clip is selectively lockingly engageable with the center post such that the lock clip substantially surrounds the center post and contacts and separates each of the lock arms, thereby preventing the lock arms from moving towards or away from one another and the center post. The clip detents contact and lockingly engage with a lower edge of the center post to retain the lock clip securely in position surrounding the center post.

In another aspect of the present disclosure a combined width of the lock clip and vertical portions of the lock arms

is substantially identical to a transverse extent or length of the mounting points formed in the mounting track.

In another aspect of the present disclosure the lock spring further includes one or more of: a mechanical spring such as a coil spring, a leaf spring, a wave spring, a torsion spring, and a disk spring; or an electromagnetic actuator such as a magnet, an electromagnet, a servo, an electrohydraulic, electropneumatic, or electromechanical actuator; or a combination of the mechanical spring and the electromagnetic actuator. The lock spring biases the lock arms away from one another and away from the center post of the mounting flange.

In another aspect of the present disclosure a modular portable storage container system includes: a first container section defining a first partial volume of storage space, a second container section defining a second partial volume of storage space, each of the first and second container sections having a structural frame, and a latch mechanism selectively retaining the structural frame of each of the first container section and the second container section against an infrastructure substrate. The latch mechanism includes: a spring latch, a latch receiver, and a retaining hook. One of the spring latch and the latch receiver is disposed on mounting points disposed either directly or indirectly on the infrastructure substrate while the other of the spring latch and the latch receiver is disposed on the structural frames of each of the first container section and/or the second container section. The first and second container sections are movable between at least an unlatched position and a latched position. In the unlatched position, the first and second container sections are freely movable relative to the infrastructure substrate and the mounting points and in the latched position the structural frames of each of the first and second container sections are retained in contact with the mounting points of the infrastructure substrate via the latch mechanism. The spring latch and the latch receiver are disposed opposite one another and engage with one another when the first container section and/or the second container section are in a latched position. The retaining hook engages with an outer vertical portion of the structural frame to partially rotatably retain the structural frame. The system further includes a mounting track affixed to the infrastructure substrate. The mounting track has one or more of the mounting points. The mounting flanges of the spring latch and the retaining hook are selectively, fixedly mountable to the mounting points. The system further includes at least one slide lock movable between at least an engaged position and a disengaged position. The slide lock is selectively engageable with the mounting points of the mounting track. When the at least one slide lock is in the disengaged position, the mounting flanges are movable relative to the mounting track, and when the at least one slide lock is in the engaged position, the mounting flanges are immovably secured to the mounting track. Each of the spring latch and the retaining hook include mounting flanges that are selectively mountable to the mounting points of the mounting track in one or more positions defined by a size of the first container section, or a size of the second container section.

In another aspect of the present disclosure the infrastructure substrate includes at least one of: walls and floors of buildings, walls and floors of vehicles or vehicle cargo compartments; stakes of a stake truck; an interior or exterior wall of a semi or semi tractor trailer; a wall or interior surface of an aircraft or aircraft fuselage; a wall or interior surface of a watercraft; a wall or interior surface of a train

or train car; interior walls, doors, and floors of shipping containers; interior walls, doors, and floors of shipping crates.

In another aspect of the present disclosure each of the at least one slide locks further includes a lock housing fixed to the mounting flanges, lock arms movably disposed within the lock housing, and a lock spring disposed within the lock housing, and between the lock arms. The lock spring biases the lock arms away from each other. The lock arms lockingly engage with the mounting points of the mounting track and immobilize the slide lock relative to the mounting track in the engaged position.

In another aspect of the present disclosure each of the at least one slide locks further includes a lock clip, the lock clip having clip arms extending from a clip base to clip detents. The clip arms are substantially parallel to one another, and substantially orthogonal to the clip base. The clip detents, clip base, and clip arms are sized and shaped to surround and lockingly engage with a center post of the mounting flange.

20 The center post of the mounting flange is located between the lock arms.

In another aspect of the present disclosure in the disengaged position, the lock arms are movable towards and away from the center post. In the engaged position, the lock clip is selectively lockingly engageable with the center post such that the lock clip substantially surrounds the center post and contacts and separates each of the lock arms, thereby preventing the lock arms from moving towards or away from one another and the center post. The clip detents contact and 30 lockingly engage with a lower edge of the center post to retain the lock clip securely in position surrounding the center post.

In another aspect of the present disclosure a combined width of the lock clip and vertical portions of the lock arms is substantially identical to a transverse extent or length of the mounting points formed in the mounting track.

In another aspect of the present disclosure the lock spring further includes one or more of: a mechanical spring such as a coil spring, a leaf spring, a wave spring, a torsion spring, and a disk spring; or an electromagnetic actuator such as a magnet, an electromagnet, a servo, an electrohydraulic, electropneumatic, or electromechanical actuator; or a combination of the mechanical spring and the electromagnetic actuator. The lock spring biases the lock arms away from one another and away from the center post of the mounting flange.

In another aspect of the present disclosure a modular portable storage container system includes a first container section defining a first partial volume of storage space, and 50 a second container section defining a second partial volume of storage space, each of the first and second container sections having a structural frame. The system further includes a latch mechanism selectively retaining the structural frame of each of the first container section and the second container section against an infrastructure substrate. The latch mechanism having a spring latch; a latch receiver; and a retaining hook. One of the spring latch and the latch receiver is disposed on mounting points disposed either directly or indirectly on the infrastructure substrate while the 55 other of the spring latch and the latch receiver is disposed on the structural frames of each of the first container section and/or the second container section. The system further includes a mounting track affixed to the infrastructure substrate. The mounting track has one or more of the mounting points, the mounting flanges of the spring latch. The retaining hook is selectively, fixedly mountable to the mounting points. The system further includes at least one slide lock

movable between at least an engaged position and a disengaged position. The slide lock is selectively engageable with the mounting points of the mounting track. The slide lock includes a lock housing fixed to the mounting flanges, lock arms having substantially L-shaped profiles. The lock arms are disposed opposite one another and face away from one another. The lock arms movably disposed within the lock housing. A lock spring is disposed within the lock housing and between the lock arms. The lock spring biasing the lock arms away from each other. A lock clip has clip arms extending from a clip base to clip detents. The clip arms are substantially parallel to one another and substantially orthogonal to the clip base. The clip detents, clip base, and clip arms are sized and shaped to surround and lockingly engage with a center post of the mounting flange. The center post of the mounting flange is located between the lock arms. When the at least one slide lock is in the disengaged position, the mounting flanges are movable relative to the mounting track, and when the at least one slide lock is in the engaged position, the mounting flanges are immovably secured to the mounting track by the lock arms lockingly engaging with the mounting points of the mounting track and immobilizing the slide lock relative to the mounting track in the engaged position. The first and second container sections are movable between at least an unlatched position and a latched position. In the unlatched position, the first and second container sections are freely movable relative to the infrastructure substrate and the mounting points. In the latched position the structural frames of each of the first and second container sections are retained in contact with the mounting points of the infrastructure substrate via the latch mechanism. The spring latch and the latch receiver are disposed opposite one another and engage with one another when the first container section and/or the second container section are in a latched position. The retaining hook engages with the structural frame to partially rotatably retain the structural frame. Each of the spring latch and the retaining hook include mounting flanges that are selectively mountable to the mounting points of the infrastructure substrate in one or more positions defined by a size of the first container section, or a size of the second container section.

In another aspect of the present disclosure the infrastructure substrate comprises at least one of: walls and floors of buildings, walls and floors of vehicles or vehicle cargo compartments; stakes of a stake truck; an interior or exterior wall of a semi or semi tractor trailer; a wall or interior surface of an aircraft or aircraft fuselage; a wall or interior surface of a watercraft; a wall or interior surface of a train or train car; interior walls, doors, and floors of shipping containers; interior walls, doors, and floors of shipping crates.

In another aspect of the present disclosure in the disengaged position, the lock arms are movable towards and away from the center post. In the engaged position, the lock clip is selectively lockingly engageable with the center post such that the lock clip substantially surrounds the center post and contacts and separates each of the lock arms, thereby preventing the lock arms from moving towards or away from one another and the center post. The clip detents contact and lockingly engage with a lower edge of the center post to retain the lock clip securely in position surrounding the center post. A combined width of the lock clip and vertical portions of the lock arms is substantially identical to a transverse extent or length of the mounting points formed in the mounting track.

In another aspect of the present disclosure the lock spring further includes one or more of: a mechanical spring such as:

a coil spring, a leaf spring, a wave spring, a torsion spring, and a disk spring; or an electromagnetic actuator such as: a magnet, an electromagnet, a servo, an electrohydraulic, electropneumatic, or electromechanical actuator; or a combination of the mechanical spring and the electromagnetic actuator, wherein the lock spring biases the lock arms away from one another and away from the center post of the mounting flange.

Further areas of applicability will become apparent from the description provided herein. It should be understood that the description and specific examples are intended for purposes of illustration only and are not intended to limit the scope of the present disclosure.

15 BRIEF DESCRIPTION OF THE DRAWINGS

The drawings described herein are for illustration purposes only and are not intended to limit the scope of the present disclosure in any way.

FIG. 1 is a partial perspective rear view of a modular portable storage container system according to an aspect of the present disclosure;

FIG. 2 is a partial perspective front view of the modular portable storage container system of FIG. 1 according to an aspect of the present disclosure;

FIG. 3 is a partial perspective rear cutaway view of a portion of the modular portable storage container system of FIG. 1 in an open position and showing articulation of a lock arm according to an aspect of the present disclosure;

FIG. 4 is a partial rear cutaway view of a portion of the modular portable storage container system of FIG. 3 in a closed position and showing the lock arm in a locked position according to an aspect of the present disclosure;

FIG. 5 is a partial perspective cutaway view of the modular portable storage container system of FIG. 3 showing a fluted portion of a lock track and the lock arm partially engaged therewith according to an aspect of the present disclosure;

FIG. 6 is a partial perspective cutaway view of the modular portable storage container system of FIG. 3 showing a cross section of a portion of a lock handle and pivot shaft according to an aspect of the present disclosure;

FIG. 7 is a perspective side view of the modular portable storage container system of FIG. 1 showing a ramp in an extended according to an aspect of the present disclosure;

FIG. 8 is a partial perspective side view of the modular portable storage container system of FIG. 7 showing the ramp in an unextended or stowed position according to an aspect of the present disclosure;

FIG. 9A is a partial perspective rear view of a modular portable storage container system having a brake mechanism and latch mechanism according to an aspect of the present disclosure;

FIG. 9B is a partial perspective rear view of a second embodiment of a modular portable storage container system having a brake mechanism and a latch mechanism according to an aspect of the present disclosure;

FIG. 10A is a partial perspective rear view of a portion of the brake mechanism of the modular portable storage container system of FIGS. 9A and 9B according to an aspect of the present disclosure;

FIG. 10B is a partial perspective side view of a portion of the brake mechanism of FIG. 10A depicting a spring-loaded retainer according to an aspect of the present disclosure;

FIG. 11A is a partial perspective rear view of a portion of the modular portable storage container system depicting the latch mechanism according to an aspect of the present disclosure;

FIG. 11B is a partial perspective cross-sectional view of the latch mechanism of FIG. 11A according to an aspect of the present disclosure;

FIG. 11C is a partial perspective rear view of a portion of the modular portable storage container system depicting an alternate latch mechanism according to an aspect of the present disclosure;

FIG. 12A is a partial perspective cross-sectional view of the modular portable storage container system of FIG. 9A depicting a retaining hook according to an aspect of the present disclosure;

FIG. 12B is a partial perspective top view of a portion of the modular portable storage container system of FIG. 9B depicting a retaining hook according to an aspect of the present disclosure;

FIG. 13 is a partial perspective cross-sectional view of a portion of a blocking frame and a portion of a structural frame of a modular portable storage container system according to an aspect of the present disclosure;

FIG. 14 is a partial perspective view of a modular portable storage container system having blocking frame mounted shelves according to an aspect of the present disclosure;

FIG. 15 is a partial perspective view of a modular portable storage container system having an engagement indicator system with position sensors and position indicators according to an aspect of the present disclosure;

FIG. 16A is a partial perspective internal front view of a position sensor of the modular portable storage container system of FIG. 15 according to an aspect of the present disclosure;

FIG. 16B is a partial perspective internal rear view of a position sensor of the modular portable storage container system of FIG. 15 according to an aspect of the present disclosure;

FIG. 16C is a partial perspective external rear side view of a position sensor of the modular portable storage container system of FIG. 15 according to an aspect of the present disclosure;

FIG. 17 is a partial perspective view of a modular portable storage container system having a latch mechanism having mounting flanges, the latch mechanism retaining a structural frame of a modular portable storage container system to mounting points according to an aspect of the present disclosure;

FIG. 18A is a partial perspective view of a spring latch of the latch mechanism of FIG. 17, the spring latch including a mounting flange for mounting the spring latch to the mounting points according to an aspect of the present disclosure;

FIG. 18B is a partial perspective view of a retaining hook of the latch mechanism of FIG. 17, the retaining hook including a mounting flange for mounting the spring latch to the mounting points according to an aspect of the present disclosure;

FIG. 19A is a partial perspective view of a disengaged position of a slide lock of the modular portable storage container system of FIG. 17, the slide lock affixed to the mounting flanges and movable between at least the disengaged position and an engaged position, the slide lock including a selectively removable lock clip according to an aspect of the present disclosure; and

FIG. 19B is a partial perspective view of the engaged position of a slide lock of the modular portable storage

container system of FIG. 19A, the slide lock according to an aspect of the present disclosure.

DETAILED DESCRIPTION

The following description is merely exemplary in nature and is not intended to limit the present disclosure, application, or uses.

In the text that follows, including in the claims and specification, certain elements are designated as "first", "second", "third", "fourth", and so forth. These are arbitrary designations intended to be consistent only in the section in which they appear, i.e. the specification or the claims or the summary, and are not necessarily consistent between the specification, the claims, and the summary. In that sense they are not intended to limit the elements in any way and a "second" element labeled as such in the claim may or may not refer to a "second" element labeled as such in the specification. Instead, the elements are distinguishable by their disposition, description, connections, and function.

Referring to FIGS. 1 and 2, a modular portable storage container system 10 is shown. The system 10 is sized and shaped to fit within a vehicle (not specifically shown). The vehicle may be any of a wide variety of vehicles such as cars, vans, trucks, busses, motor homes, semi trucks and/or trailers, trains, aircraft, spacecraft, watercraft, or any other such vehicle without departing from the scope or intent of the present disclosure. More specifically, the system 10 is sized and shaped to fit within a vehicle cargo compartment 30 (not specifically shown except for cargo floor 12). The system 10 is portable and can be moved or manipulated from place to place by one or more people, or by automated means. The system 10 includes a modular storage container 14 composed of at least a first container section 16 and a second container section 18.

In the context of the modular portable storage container system 10 and vehicle cargo compartments into which the system 10 is designed to fit, the terms "forward", "rear", "inner", "inwardly", "outer", "outwardly", "above", and "below" are terms used relative to the orientation of a vehicle as shown in the drawings of the present application. Thus, "forward" refers to a direction toward a front of a vehicle, "rearward" refers to a direction toward a rear of a vehicle, "inner" and "inwardly" refers to a direction towards the interior of a vehicle, and "outer" and "outwardly" refers to a direction towards the exterior of a vehicle, "below" refers to a direction towards the bottom of the vehicle, and "above" refers to a direction towards a top of the vehicle.

The terms "top", "overtop", "bottom", "side" and "above" are terms used relative to the orientation of storage container 14 as shown in the drawings of the present application. Thus, while the orientation of the storage container 14 may change with respect to a given use, these terms are intended to still apply relative to the orientation of the components of the storage container 14 as shown in the drawings.

The storage container 14 may be used in a variety of different applications without departing from the scope or intent of the present disclosure. For example, the storage container 14 may be used in a warehouse or factory setting 60 to move items from one area of the warehouse or factory to another. The storage container 14 may likewise be used in delivery applications in which the storage container 14 is loaded with items at one location. Subsequently, the storage container 14 is moved into the vehicle cargo compartment, 65 secured therein, and then transported by the vehicle to another location where the storage container 14 or the contents thereof are delivered to the new location.

In order to move or manipulate the storage container 14 from place to place, including into and out of vehicle cargo compartments, one or more handles 20 are built into an exterior surface 22 of the storage container 14. The handles 20 may be moulded unitarily with the storage container 14, or the handles 20 may be affixed to the storage container 14 by known means such as mechanical fasteners including bolts, nuts, rivets, screws, interference fittings, and the like, and/or thermal or chemical fastening means such as welding, braising, glues, or the like. The handles 20 shown in FIGS. 1 and 2 are angled with respect to the horizontal to provide an ergonomic hand-position or grip for a person or people moving the storage container 14, however, it should be appreciated that the angles shown are merely exemplary and not intended to be limiting. In some examples, the handles 20 may be completely horizontal, completely vertical or angled anywhere in between. Likewise, the handles 20 shown are linear, but could also be curved, angular, or the like without departing from the scope or intent of the present disclosure. In some examples, in which the storage container 14 is moved from place to place solely by automated means, the handles 20 may adapted as a keyway for a robotic or otherwise automated assembly to movably attach to and manipulate or move the storage container 14 from location to location. Additional handles 20, keyways, or other such features may be disposed at locations other than those shown in the figures without departing from the scope or intent of the present disclosure.

As shown in FIGS. 1 through 4, the first and second container sections 16, 18 define rectilinear prisms each having an open side 24. Put differently, the first and second container sections 16, 18 of FIGS. 1 and 2 are shaped generally like open-sided rectangular boxes. In several aspects, the first and second container sections 16, 18 are substantially identical to one another. In some examples, the first and second container sections 16, 18 define mirror images of one another. The open side 24 of the first container section 16 and the open side 24' of the second container section face each other so that when the first and second container sections 16, 18 are placed into contact with one another in a closed position 26, the first and second container sections 16, 18 surround, enclose, and define a full volume 28 of storage space. That is, the first container section 16 defines a first partial volume 30 of storage space, and the second container section 18 defines a second partial volume 32 of storage space, the first and second partial volumes 30, 32 of storage space combining to define the full volume 28 of storage space.

Each of the first and second container sections 16, 18 may be made of a wide variety of different materials, including metals, alloys, plastics, vinyls, composite materials, and the like. In one particular example, the first and second container sections 16, 18 are made in a vacuum formed injection molding process out of a plastic material such as polytetrafluoroethylene (PTFE), or the like. In another specific example in which the modular storage container system 10 is used in food or medical applications, the materials of the first and second container sections 16, 18 and many or all of their components are composed of known food safe or medical grade materials. The material of the first and second container sections 16, 18 are at least partially solid, hollow, corrugated or a honeycomb material, or the like without departing from the scope or intent of the present disclosure.

The first and second container sections 16, 18 of some examples are made of several distinct modular components. In one example, the first container section 16 is formed of a modular first end portion 34, a modular second end portion

36, and a modular first wall portion 38. The first end portion 34 defines a rear end 40 of the first container section 16, while the second end portion 36 defines a front end 42 of the first container section 16, with the modular first wall portion 38 extending therebetween. That is, the first and second end portions 34, 36 are substantially planar and parallel to one another, while the first wall portion 38 is orthogonal to each of the first and second end portions 34, 36. The first end portion 34 contacts the first wall portion 38 at a connection surface 43 where fastening means are employed to secure the first end portion 34 to the first wall portion 38. Likewise, the second end portion 36 contacts the first wall portion 38 at a connection surface 43 where fastening means are employed to secure the second end portion 36 to the first wall portion 38. The fastening means, while not specifically shown, may include mechanical fasteners including bolts, nuts, rivets, screws, press-fit fasteners, clasps, interference fittings, or the like, or by and/or thermal or chemical fastening means such as welding, braising, glues, or the like.

In some examples, the first wall portion 38 is composed of multiple modular sections or components such as a modular top section 44 forming an enclosing top 46 of the first wall portion 38, a horizontal bottom or base portion 48 forming an enclosing bottom 50 of the first wall portion 38, and a vertical wall 52. Each of the base portion 48, top section 44, and vertical wall 52 are connected by one or more fastening means as described above. More specifically, the top section 44, base portion 48 and vertical wall 52 contact one another at one or more connection surfaces 53, where the fastening means are employed to secure the modular top section 44, base portion 48, and vertical wall 52 together. In further examples, the first wall portion 38 may be a unitary construction or molding having a substantially rectangular "C"-shaped cross section defining the modular top section 46, base portion 48, and vertical wall 52 portions.

Like the first container section 16, the second container section 18 is formed of a modular third end portion 54, a modular fourth end portion 56, and a modular second wall portion 58. The third end portion 54 contacts the second wall portion 58 at a connection surface 43 where fastening means as described above are employed to secure the third end portion 54 to the second wall portion 58. Likewise, the fourth end portion 56 contacts the second wall portion 58 at a connection surface 43 where fastening means are employed to secure the fourth end portion 56 to the second wall portion 58.

The third end portion 54 defines a rear end 40' of the second container section 18, while the fourth end portion 56 defines a front end 42' of the second container section 18, with the modular second wall portion 58 extending therebetween. The second wall portion 58 may be composed of a variety of modular components similar to those described above with respect to the first wall portion 38, or like the first wall portion 38, may be composed of a single unitary moulding or the like.

In several aspects, the base portion 48 of each of the first and second container sections 16, 18 has a concave arcuate shape extending from the first end portion 34 to the second end portion 36 of the first wall portion 38, and extending from the third end portion 54 to the fourth end portion 56 of the second wall portion 58. The concave arcuate shape of some examples is interrupted by at least two inset sections 59 sized and shaped to fit around wheel well intrusions in a vehicle cargo compartment. The two inset sections 59 allow for the storage container 14 to be loaded into a vehicle cargo compartment in either direction without fouling against the wheel well intrusions in the vehicle cargo compartment.

11

That is, the front and rear ends 42, 42' and 40, 40' of the storage container 14 are reversible such that the storage container 14 can be loaded into the vehicle cargo compartment in either a "forward" or "backward" direction. The base portion 48 further includes a plurality of wheels or casters 61. The casters 61 of some examples are disposed on a bottom surface 63 of the base portion 48 and provide the first and second container sections 16, 18 the ability to roll from place to place. The casters 61 are attached to the base portion 48 by known means such as mechanical fasteners including bolts, nuts, rivets, screws, press-fit fasteners, clasps, interference fittings, or the like. In several aspects, the casters 61 are made of one or more materials including but not limited to: metals, alloys, plastics, vinyls, composite materials, and the like.

In some aspects, the fastening means may also be movable devices such as hinges, accordion-folded attachments, or the like. Likewise, some or all of the first and second wall portions 38, 58 and the first, second, third, and fourth end portions 34, 36, 54, 56, and the top sections 46 and base portions 48 may be made up of multiple independent sections hinged, accordion-folded, or otherwise movably attached to one another. In an example of a food truck, one or more of the first and second wall portions 38, 58 may be formed of two longitudinally-extending sections, one disposed overtop the other and attached to one another at a horizontal hinge. The longitudinally-extending section disposed towards the top section 46 is thereby allowed to rotate downwards and towards the base portion 48, thus forming an opening through which food or other materials may be passed from the interior of the vehicle cargo compartment to customers outside the vehicle. Similarly, in a camping situation, the multiple independent sections may be expandable via accordion-fold attachments to allow the storage container 14 to be expanded substantially beyond the dimensions of the vehicle cargo compartment when the storage container 14 is outside the vehicle cargo compartment and unlocked.

The first and second partial volumes 30, 32 of storage space within the first and second container sections 16, 18 may be organized or sub-divided in a variety of different ways using modular organizational components 60. The organizational components 60 are affixed to the first and second container sections 16, 18 by any of a variety of known fastening means, such as mechanical fasteners including bolts, nuts, rivets, screws, press-fit fasteners, clasps, interference fittings, or the like. In the example of FIG. 1, the second partial volume 32 of storage space within the second container section 18 is divided by one or more shelves 62. The shelves 62 may be attached to the modular third and fourth end portions 54, 56, and/or the second wall portion 58 of the second container section 18.

In some aspects, some of the shelves 62 extend fully from the third end portion 54 to the fourth end portion 56. In other aspects, some shelves 62 extend only part of the distance between the third end portion 54 and the fourth end portion 56, thereby providing increased vertical space for stowage of tall items such as buckets 64, bar stock, brooms, shovels, or the like. Similar shelves 62 or other such structures may be affixed within the first partial volume 30 of storage space in the first container section 16. While in the foregoing, shelves 62 have been described as a means of organization within the first and second partial volumes 30, 32 of storage space, it should be appreciated that shelves 62 are intended as a non-limiting example. Other organizational structures may be used in one, the other, or both of the first and second partial volumes 30, 32 without departing from the scope or

12

intent of the present disclosure. In several examples, additional or different organizational components 60 used may include shelves 62, cabinets, walls, drawers, hooks, bars, cages, clothes racks, or any of a variety of other such organizational components 60 without departing from the scope or intent of the present disclosure. Furthermore, the organizational components 60 may have particular adaptations for a given purpose. For example, some shelves 62 may be equipped with a lip, edge, or recesses for spill prevention, liquid retention, or the like. Likewise, the same types of organizational components 60 may be used in each of the first and second container sections 16, 18, or the first and second container sections 16, 18 may each have unique organizational components 60 disposed therein.

Turning now more specifically to FIGS. 3-6 and with continuing reference to FIGS. 1-4, the first and second container sections 16, 18 are movable relative to one another between at least the closed position 26 and an open position 66. In the open position 66, the first and second container sections 16, 18 are effectively independent of one another, and may be moved entirely separately from one another. In an example, the first and second container sections 16, 18 may be loaded with cargo, for example, buckets 64, packages for delivery (not specifically shown), or the like in entirely different locations within a factory or warehouse. The first and second container sections 16, 18 may then be moved to a single location for loading into delivery vehicles, at which time, the first and second container sections 16, 18 are moved into the closed position 26 and loaded into a vehicle together. In order to secure the first and second container sections 16, 18 together, the storage container 14 has a locking mechanism 68.

The locking mechanism 68 has four primary components: a lock handle 70, a lock arm 72, a pivot shaft 74, and a lock track 76. As shown in the drawings, in several aspects, each of the first and second container sections 16, 18 includes distinct portions of the locking mechanism 68, however, it should be appreciated that variations in which each of the first and second container sections 16, 18 includes all of the locking mechanism 68 components are intended to be included in the scope of the present disclosure. One copy of the locking mechanism 68 is described in further detail below, however, it should be appreciated that the storage container 14 may be equipped with a single locking mechanism 68 or any number of additional locking mechanisms 68 without departing from the scope or intent of the present disclosure. For example, the locking mechanism 68 may be located only at the front and rear ends 42, 42' and 40, 40' of the storage container 14, at only one of the front and rear ends 42, 42', 40, 40' or there may be additional locking mechanisms 68 disposed throughout the storage container 14, such as within a dividing wall (not specifically shown) disposed within the storage container 14 and parallel to the end portions 34, 36, 54, 56 of the storage container 14. In a particular example, a first locking mechanism 68' is disposed at the front end 42, 42' of the storage container 14, and a second locking mechanism 68" is disposed at the rear end 40, 40' of the storage container 14.

The pivot shaft 74 is a horizontally and longitudinally-disposed cylindrical rod, torsion tube, or torque tube that is freely rotatable within a set of bearings 78 disposed in the first and second end portions 34, 36 of the first container section 16. The pivot shaft 74 defines an axis of rotation for the lock handle 70, and lock arm 72. In food and/or medical applications, the bearings 78 are food safe or medical grade sealed bearings 78. More specifically, as shown in FIG. 7, the pivot shaft 74 extends fully from a point exterior to the

13

first end portion **34**, through the first end portion **34**, through the first partial volume **30** of storage space through the second end portion **36** to a point exterior to the second end portion **36**. In several aspects, the pivot shaft **74** extends through a portion of one or more of the shelves **62**. The external extremities or ends **80** of the pivot shaft **74** engage with and are fixed for common rotation with lock handles **70**. Similarly, the lock arm **72** is fixed for common rotation with the pivot shaft **74**. The lock handle **70**, lock arm **72**, and pivot shaft **74** are rotatable between at least an unlocked position **82** and a locked position **84**. The lock arm **72** is located at least partially within a hollow area **86** formed within each of the first and second end portions **34**, **36**. The lock arm **72** extends radially outwardly from the pivot shaft **74** to a roller assembly **88**. The roller assembly **88** is sized and shaped to fit within and engage with the lock track **76**.

In several aspects, the lock track **76** is a roll-formed component formed of galvanized steel, aluminum, composite materials, or the like. The lock track **76** of some examples includes at least three separate sections, at least two of which are disposed in a second hollow area **87** formed the second container section **18**, while the third is disposed in the hollow area **86** of the first container section **16**. More specifically, the lock track **76** within the first container section **16** consists of a curvilinear storage section **90**. The storage section **90** is disposed within the first and second end portions **34**, **36**. The curvilinear storage section **90** forms an arc section of a substantially circular section of lock track **76** that is substantially identical in radius to the distance defined by the length of the lock arm **72** between the pivot shaft **74** and the roller assembly **88**. When the lock arm **72** is in the unlocked position **82**, the roller assembly **88** is disposed within the storage section **90** of lock track **76** within the first container section **16**, and the first and second container sections **16**, **18** are freely movable relative to one another.

By contrast, when the open side **24** of the first container section **16** and the open side **24** of the second container section **18** are facing one another, and the first and second container sections **16**, **18** are correctly spaced apart from one another, the lock arm **72** can be rotated to engage with the two remaining lock track **76** sections. The two remaining lock track sections **76** are disposed in the second container section **18**, and specifically within the third and fourth end portions **54**, **56**. The remaining lock track **76** sections are a fluted open portion **92** and a closed end portion **94** with a continuous track portion **93** disposed therebetween. The fluted open portion **92** is a curvilinear section of the lock track **76** which opens towards the first container section **18** and is located at a height below the height at which the curvilinear storage section **90** is disposed within the first container section **16**. In several aspects, the fluted open portion **92** has larger and/or wider dimensions at the portion facing and proximate the first container section **16** and narrows to a smaller and/or narrow set of dimensions at a portion farther within the second container section **18** and farther away from the first container section **16**. The fluted open portion **92** is thus sized and shaped to capture the roller assembly **88** of the lock arm **72** as the lock arm **72** is rotated towards the second container section **18** from the unlocked position **82** towards the locked position **84**. The fluted or widened shape of the fluted open portion **92** allows for some positioning error of the first and second container sections **16**, **18** relative to one another without disrupting the efficacy of the locking mechanism **68**. In several aspects, farther from the first container section **16**, and deeper within the

14

second container section **18**, the fluted open portion **92** straightens into a less acutely curved section of the lock track **76**.

At its farthest extent within the second container section **18**, the fluted open portion **92** meets the continuous track portion **93** of the lock track **76**. The continuous track portion **93** has a substantially consistent cross-sectional size along its entire length all the way from the fluted open portion **92** to the closed end portion **94**. The continuous track portion **93** is a substantially linear section of lock track **76** which extends at an angle **95** downwards and away from the first container section **16**. The closed end portion **94** is disposed at a downward-most end of the continuous track portion **93** proximate the base portion **48** of the second container section **18**. The precise angle **95** at which the continuous track portion **93** extends downwards and away from the first container section **16** may vary from application to application without departing from the scope or intent of the present disclosure. As the lock arm **72** is moved from the unlocked position **82** to the locked position **84**, the lock arm **72** traverses the space between the first and second container sections **16**, **18** and the roller assembly **88** is captured by the fluted open portion **92**. Once captured, the roller assembly **88** is centered by and rolls within the fluted end portion **92** downwards, through the continuous track portion **93** and towards the closed end portion **94**. As a user continues to actuate the lock handle **70** from the unlocked position **82** towards the locked position **84** while the roller assembly **88** is in the fluted open portion **92**, the fluted open portion **92** directs the roller assembly **88** into the continuous track portion **93**, and eventually to the closed end portion **94**. The downward angle **95** at which the continuous track portion **93** extends causes the roller assembly to exert a closing force "F" between the lock track **76** and the pivot shaft **74**, thereby drawing the first and second container sections **16**, **18** closer together. As the roller assembly **88** of the lock arm **72** approaches the terminus of the closed end portion **94** proximate the base portion **48** of the second container section **18**, the first and second container sections **16**, **18** are drawn forcibly into contact with one another such that the first and third end portions **34**, **54**, and the second and fourth end portions **36**, **56** are in contact with one another. Likewise, the base portions **48** and the top sections **46** of each of the first and second container sections **16**, **18** are drawn into contact with one another in the locked position **84**. Additional locking features such as padlocks, pins, locking rings, or the like may then retain and secure the lock handle **70**, and/or the lock arm **72**, and/or the pivot shaft **74** and therefore the entire locking mechanism **68** in the locked position **84**. When locked, the additional locking features prevent accidental or unwanted movement of the first and second sections **16**, **18** relative to one another. In several aspects, because the locking mechanism **68** is disposed at both the front and rear ends **42**, **42'** and **40**, **40'** of the storage container **14**, the locking mechanism **68** rigidly retains the first and second container sections **16**, **18** against one another, allowing the storage container **14** to be moved from place to place without the container sections **16**, **18** separating from one another.

The modular portable storage container system **10** further includes a blocking frame **100**. The blocking frame **100** is sized and shaped to fit within a vehicle cargo compartment and secures the first and second container sections **16**, **18** within the cargo compartment. Accordingly, the precise size and shape of the blocking frame **100** may therefore vary substantially from application to application, as the size and shape of a particular cargo compartment may vary substantially.

15

tially from vehicle to vehicle. The blocking frame 100 is immovably secured within the cargo compartment by known means, such as mechanical fasteners including bolts, nuts, rivets, screws, interference fittings, and the like, and/or thermal or chemical fastening means such as welding, braising, glues, or the like. In some examples, multiple blocking frames 100 may be used in a single cargo compartment, while in other examples, only a single blocking frame 100 may be necessary. The blocking frame 100 can be made of a number of different types of materials, and in a variety of different manufacturing processes without departing from the scope or intent of the present disclosure. In several aspects, the blocking frame 100 consists primarily of a front frame portion 102 connected to a rear frame portion 104 by a plurality of longitudinal bars 106. The front frame portion 102, rear frame portion 104 and longitudinal bars 106 of one example are metal extrusions, castings, or the like and are secured to one another by known means such as mechanical fasteners including bolts, nuts, rivets, screws, interference fittings, and the like, and/or thermal or chemical fastening means such as welding, braising, glues, or the like.

In several aspects, the blocking frame 100 is expandable. The expandable nature of the blocking frame 100 allows similar or identical blocking frame 100 components to be manufactured for use in a variety of applications. That is, because the blocking frame 100 of some examples is expandable, the same blocking frame components may be used in a space-efficient manner within a vehicle cargo compartment having a volume substantially smaller than the volume of a second vehicle cargo compartment. However, the expandable blocking frame 100 allows the same front and rear frame portions 102, 104 and longitudinal bars 106 in an expanded position within the second vehicle cargo compartment as well. Likewise, the expandable blocking frame 100 allows the same blocking frame 100 assembly with storage containers 14 of varying sizes for use in different applications. That is, the expandable blocking frame 100 is expandable from a first configuration to a second configuration having dimensions substantially larger than the first configuration, or any of a variety of configurations therebetween.

More specifically, in an expandable example of the blocking frame 100, each of the front frame portion 102, rear frame portion 104, and longitudinal bars 106 is composed of interlocking frame segments 107. In the example shown in the figures, the interlocking frame segments 107 are telescoping bar portions having a plurality of detents 109 and locking pins 111. The locking pins 111 may be any of a variety of known pin-like features including, but not limited to: bolts and nuts, rivets, screws, interference fittings, press-fit fasteners, spring pins, cotter pins, screws, or the like. The locking pins 111 are sized and shaped to interact with the detents 109 to secure interlocking frame segments 107 of the front frame portion 102, and/or rear frame portion 104 and/or longitudinal bars 106 to other interlocking frame segments 107 of each of the front, rear, and longitudinal bar 102, 104, 106 portions of the blocking frame 100.

Each of the plurality of detents 109 is spaced apart from the next of the plurality of detents 109 by a predetermined distance. In a particular example, the spacing between each of the plurality of detents 109 is approximately one inch. However, it should be appreciated that in a one inch separation between the detents 109 is merely intended to be an exemplary arrangement, and variations in distance between the detents 109 of other examples are intended to be within the scope of the present invention. In still further examples, the interlocking frame segments 107 may be attached to one

16

another by any of a variety of known movable but lockable mechanisms, including but not limited to the above-described detents 109 and locking pins 111, as well as hinges, press-fit locking features, or the like.

5 The front frame portion 102 is disposed towards the front of the vehicle cargo compartment and includes one or more blocking members 108 forming a narrow door frame 110. The narrow door frame 110 is sized to allow a user, such as a vehicle driver or an automated robotic device to pass at 10 least partially through the narrow door frame 110 to access the storage container 14. However, even when the storage container 14 is in the closed position 26, the storage container 14 is too wide to fit through the narrow door frame 110. That is, the blocking members 108 prevent longitudinal 15 movement of the storage container 14, and even the first and second container sections 16, 18 within the vehicle cargo compartment while also allowing a user to pass into a space between the first and second container sections 16, 18 when the first and second container sections 16, 18 are in the open 20 position 66.

The rear frame portion 104 is disposed towards the rear of the vehicle cargo compartment and defines a wide door frame 112. The wide door frame 112 is larger, and specifically significantly wider than the narrow door frame 110. 25 The wide door frame 112 is sized to allow passage of the storage container 14 when the first and second container sections 16, 18 are in the closed position 26. In some examples, the rear frame portion 104 further includes one or more leg portions 113. The leg portions 113 extend laterally 30 inward and towards a centerline of the vehicle cargo compartment. In several aspects, the leg portions 113 are spaced apart by a distance sufficient to allow passage of the storage container 14 when the first and second container sections 16, 18 are in the closed position 26.

The plurality of longitudinal bars 106 provide end-to-end support for the front and rear frame portions 102, 104 while spacing the front and rear frame portions 102, 104 apart by a distance substantially similar to, but slightly larger than longitudinal dimensions of the storage container 14.

40 The blocking frame 100 also has a lock bar 114. The lock bar 114 is rotatably mounted to the blocking frame 100 and is rotatable between a locked bar position 116 and an unlocked bar position 118. More specifically, the lock bar 114 is mounted to the blocking frame 100 approximately 45 centrally above one or more of the narrow door frame 110 and the wide door frame 112, and extends laterally across a portion of the vehicle cargo compartment. The lock bar 114 may be manually or automatically operated without departing from the scope or intent of the present disclosure. In several aspects, when the lock bar 114 is in the unlocked bar position 118, the lock bar 114 is stowed up and proximate a 50 ceiling (not specifically shown) of the vehicle cargo compartment. Thus, in the unlocked bar position 118, the storage container 14 in the closed or open positions 26, 66, may be moved freely within the blocking frame 100. However, when the first and second container sections 16, 18 are in the open position 66 and separated fully from one another such that the first and second container sections 16, 18 are up against the longitudinal bars 106 of the vehicle cargo compartment, the lock bar 114 may be freely moved into the 55 locked bar position 116. In the locked bar position 116, the lock bar 114 is rotated downwards so that it defines a substantially vertical planar surface extending laterally across a portion of one or more of the narrow door frame 110 and the wide door frame 112. In the locked bar position 116, the lock bar 114 touches and engages with each of the first and second container sections 16, 18, and immobilizes the 60 65

first and second container sections 16, 18, relative to one another and the blocking frame 100. Accordingly, in the locked bar position 116, the lock bar 114 retains the first and second container sections 16, 18 in the open position 66 within the cargo compartment of the vehicle, thereby allowing users access to contents of each of the first and second container sections 16, 18 while preventing lateral movement of the first and second container sections 16, 18 while the vehicle is in motion. Likewise, the front and rear frame portions 102, 104, and the longitudinal bars 106 prevent both longitudinal and lateral movement of the first and second container sections 16, 18 when the lock bar 114 is in the locked bar position 116.

In several aspects, the front and rear frame portions 102, 104, and the longitudinal bars 106, including the blocking members 108, and leg portions 113, may have shock absorption material disposed thereon. In some examples, the shock absorption material is composed of rubber, silicone, or other similarly flexible but semi-rigid materials. Likewise, the shock absorption material may be formed into nodes such as stoppers, padding, or the like. Furthermore, it should be appreciated that the shock absorption material is sized and shaped differently depending on the size and shape of the blocking frame 100, and the storage container 14. The shock absorption material holds or wedges the first and second container sections 16, 18 immovably in place within the vehicle cargo compartment when the lock bar 114 is in the locked position 116.

Turning now to FIGS. 7 and 8, and with continuing reference to FIGS. 1-6, in some examples, the modular portable storage container system 10 further includes an extendable ramp 120. The extendable ramp 120 may vary in size, precise location, and the like depending on the particular application in which the extendable ramp 120 is used. In several aspects, the extendable ramp 120 has a plurality of extendable sections 122. The extendable sections 122 may be foldable relative to one another, or as shown in the figures, the extendable sections 122 may telescope relative to one another. At least one of the plurality of extendable sections 122 is rotatably affixed to a vehicle proximate a vehicle tailgate opening (not specifically shown), at one or more pivot points 124. Thus, the extendable ramp 120 can be rotated between at least a stowed position 126 and an unstowed position 128. In the stowed position 126, the extendable ramp 120 is positioned substantially vertically above the pivot points 124 and the extendable sections 122 are in an unextended or stowed state such that the extendable ramp 120 has a stowed length "SL" shorter than a height "H" of the blocking frame 100.

The pivot points 124 may be any of a variety of known rotating mechanisms, including hinges or the like without departing from the scope or intent of the present disclosure. However, in one particular example, the pivot points 124 include a spring-loaded locking pin 129 and a hinge base 130. The hinge base 130 is affixed to the vehicle on or proximate the cargo floor 12. The hinge base 130 defines the pivot point 124 itself, as well as a curvilinear ramp portion 132. The curvilinear ramp portion 132 extends from a rearward-facing portion 134 of the hinge base 130 to an upward-facing portion 136. A receiver 138 is formed in the upward-facing portion 136. The receiver 138 is sized and shaped to accept and retain the spring-loaded locking pin 129 therein when the ramp is in the stowed position 126. Thus, when the extendable ramp 120 is in the stowed position 126, the spring-loaded locking pin 129 fits into the receiver 138 thereby locking the extendable ramp 120 in place in the stowed position. A user can then pull up on or

otherwise retract the spring-loaded locking pin 129 from the receiver 138 and rotate the extendable ramp 120 from the stowed position 126 to the unstowed position 128. Conversely, the spring-loaded locking pin 129 is biased into contact with the curvilinear ramp portion 132, and when the extendable ramp 120 is rotated from the unstowed position 128 to the stowed position 126, the spring-loaded locking pin 129 follows the curvilinear ramp portion to the upward-facing portion 136 where the spring-loaded locking pin 129 automatically engages with the receiver 138.

In the unstowed position 128, the extendable ramp 120 can be extended from the stowed length SL to an unstowed length "UL". The unstowed length UL may vary depending on the particular situation in which the extendable ramp 120 is being used. For example, at a loading dock, the extendable ramp 120 may not be fully extended, and may form a substantially horizontal surface from the loading dock lip (not specifically shown) to the cargo floor 12 of the cargo compartment of the vehicle. In another example, vehicle 15 may be on level ground, and the extendable ramp 120 may be unstowed to a position below the horizontal such that each of the extendable sections 122 is maximally extended and where the unstowed length UL substantially greater than the stowed length SL. In the latter example, the concave 20 arcuate shape of the base portion 48 is sized and shaped to pass over a hump 140 defining a slope or angle 142 of the extendable ramp 120 relative to the floor 12 of the cargo compartment, such that the base portion 48 does not contact or get hung up on the extendable ramp 120, the floor 12, or 25 hump 140 at which the floor 12 and extendable ramp 120 meet. In several aspects, the extendable ramp 120 is equipped with a variety of latching mechanisms which, when the extendable ramp 120 is in the unstowed position 128, lock the extendable sections 122 in place relative to one another. The latching mechanisms may be any of a variety 30 of known or novel latching mechanisms including but not limited to: cotter pins, spring pins, clamps, spring clamps, 35 spring loaded hinges, or the like.

The modular nature of the portable storage container system 10 allows for storage containers 14 of varying sizes, shapes, and the like for use in industrial applications, as well as in personal or private use. The storage containers 14 and blocking frames 100 may be sized for use in semi trucks, tractor trailers, delivery vans, mail trucks, station wagons, 40 train cars, or the like without departing from the scope or intent of the present disclosure. For some examples, the storage containers 14 and blocking frames 100 may be used in portable power station applications with a generator housed in one of the first and second container sections 16, 18 and electrical or fuel ancillaries housed in the other of the first and second container sections 16, 18. Likewise, the storage containers 14 and blocking frames 100 may be used in camping situations where the storage containers 14 are pre-loaded with camping gear (i.e. tents, tables, sleeping 45 rolls and bags, portable stove, cookware, and the like) and unstowed from a vehicle at a campsite where the first and second container sections 16, 18 are separated and their contents unstowed for users to access the camping equipment stored therein. In further examples, the first and second container sections 16, 18 may be adapted as refrigeration units for transport of food, medical supplies, mortuary units, or the like.

In some examples, multiple storage containers 14 may be placed into a single blocking frame 100 having additional 50 lock bars 114 disposed therein. Likewise the modularity of the first and second end portions 34, 36 and third and fourth end portions 54, 56 and the first and second wall portions 38,

58 means that first and second wall portions 38, 58 having different lengths for differing applications may be used with the same first, second, third, and fourth end portions 34, 36, 54, 56. Likewise, first, second, third, and fourth end portions 34, 36, 54, 56 having different widths for differing applications may be used with the first and second wall portions 38, 58 having lengths optimized for a particular application. That is, the modularity of each of the first, second, third, and fourth end portions 34, 36, 54, 56, and the first and second wall portions 38, 58 allows the same fundamental components to be used in a wide variety of different applications. of the present disclosure offers several advantages.

Furthermore, the first, second, third, and fourth end portions 34, 36, 54, 56 may be equipped as described above with a keyway or coupling mechanism. The coupling mechanism (not specifically shown) may be used to couple a storage container 14 to one or more other storage containers 14 to form a train of multiple storage containers 14. The coupling mechanism may be any of a variety of coupling mechanisms including but not limited to: Janney couplers, screw couplings, knuckle couplings, drawbars, pins and sockets, ball hitches, gooseneck hitches, pintle hitches, receiver hitches, hinged or rigid or flexible arms with coupling components, or the like. Trains of storage containers 14 can be used in warehouse applications to move quantities of goods from location to location. In further examples, the coupling mechanism may be separate from the keyway and may instead be formed in or mounted to each of the first and second container sections 16, 18, such that the first and second container sections 16, 18 may be moved separately from one another. In the latter example, the first and second container sections 16, 18 may be loaded with different materials or cargo at completely different locations within a factory or warehouse setting, or the like. The first and second container sections 16, 18 may then be manually or automatically moved from their distinct locations within the factory to a central location where the first and second container sections 16, 18 are joined together in the locked position 84 for loading into a cargo compartment of a transport vehicle.

The first and second container sections 16, 18, and/or the storage container 14 itself of some examples are stackable. That is, multiple first container sections 16 may be stacked atop one another, multiple second container sections 18 may be stacked atop one another, and/or multiple complete storage containers 14 may be stacked atop one another. In several aspects, in instances where the first and second container sections 16, 18, and/or storage container 14 are stackable, the top sections 46 are shaped to accept and partially enclose the casters 61 of the first and second container sections 16, 18, and/or storage container 14 above. Similarly, the base portion 48 may have additional contours molded therein (not specifically shown). The additional contours may be adapted to accept lifting devices, such as fork-lift prongs, or the like. Similarly, the first and second end portions 34, 36 and wall portions 38 may be formed with recesses, protrusions, or other such features sized and shaped to allow engagement with moving devices such as fork-lifts, or the like. These recesses, protrusions or the like provide a simple way for the storage containers 14 and/or separate first and second container sections 16, 18 to be moved from place to place.

Turning now to FIGS. 9A and 9B, examples of the modular portable storage container system 10 of the present disclosure are shown. In the example of FIG. 9A, the modular portable storage container system 10 includes both first and second container sections 16, 18 as described

hereinabove. In several aspects, the first and second container sections 16, 18 shown in FIG. 9A and the first container section 16 shown in FIG. 9B are composed primarily of metal or metal alloys. It should be appreciated that only part of the second container section 18 is shown in FIG. 9A, and only a first container section 16 is shown in FIG. 9B for the sake of simplicity. Specifically, the first and second container sections 16, 18 each include a structural frame 200. The structural frame 200 includes at least a front section 202 with vertical members 204 connected to a top member 206 and a bottom member 208. Similarly, the structural frame 200 includes a rear section 210 with outer vertical members 204' connected to a top member 206 and a bottom member 208. The front and rear sections 202, 210 are rigidly affixed to one another by one or more longitudinal members 212 extending from the front section 202 to the rear section 210. The front and rear sections 202, 210 are also rigidly affixed to one another by the base portion 48 which forms the bottom member 208 of each of the front and rear sections 202, 210 of each of the first and second container sections 16, 18. In some examples, and as shown in FIGS. 9A and 9B, the first and second container sections 16, 18 may include one or more shelves 62. The shelves 62 of some examples may include additional front and rear structural members 214, 216, as well as longitudinal structural members 218, 218'. The longitudinal structural members 218, 218' extend longitudinally between and are rigidly affixed to each of the front and rear sections 202, 210 of each of the first and second container sections 16, 18.

In several aspects, the structural frame 200 of the first and second container sections 16, 18 is equipped with enclosing material 219. The enclosing material 219 may be any of a wide variety of different materials including but not limited to: metals, alloys, plastics, vinyls, fabrics, composite materials, and the like. In the example shown in FIGS. 9A and 9B, the enclosing material 219 defines a wire mesh material extending between at least each of the vertical members 204, 204', top members 206, 206', longitudinal members 212, front and rear structural members 214, 216, and longitudinal structural members 218, 218', as well as extending towards and engaging with the bottom members 208. In further examples, multiple vertical portions 204, 204' may be used. That is, multiple vertical portions 204, 204' may form a portion of the ends of the structural frame 200 as shown in FIG. 9B. When multiple vertical portions 204, 204' are used, one or more of the vertical portions 204, 204' may provide both additional rigidity to the structural frame 200 as well as offering users locations which may be grasped by human hands, mechanical devices, such as robotic arms, or other such manipulation means.

In some examples, the first and second container sections 16, 18 may be equipped with one or more skirts 221. The skirts 221 are mounted to the first and second container sections 16, 18 at locations defining the bottom corners of the first and second container sections 16, 18. The skirts 221 shown in FIG. 9B define an open-sided tetrahedron in which the open side of the prism faces the casters 61 of the first and second container sections 16, 18. However, it should be appreciated that the precise shape and construction of the skirts 221 may vary from application to application and may include triangular prismatic shapes, cylindrical shapes, or any other such shapes that provide protection to the casters 61 of the first and second container sections 16, 18. That is, the skirts 221 act as guards for the casters 61, substantially preventing or diminishing the potential for physical interference with the rolling and/or spinning motion of the casters 61. The skirts 221 also provide a means to guide the

first and second container sections 16, 18 during loading and/or unloading into a vehicle cargo compartment, and/or within a warehouse, or the like.

As shown in FIGS. 9A and 9B, the base portion 48 of each of the first and second container sections 16, 18 is equipped with a brake mechanism 220. The brake mechanism 220 consists of a brake pedal 222 rotatable about a brake pivot shaft 224. The brake pedal 222 is also connected to a brake pad 226 via an actuator rod 228 which is slidably disposed within a sleeve 230. The brake pivot shaft 224 extends longitudinally through the base portion 48 and protrudes through and beyond the confines of the base portion 48 at the front and rear sections 202, 210 of each of the first and second container sections 16, 18. The brake mechanism 220 may be formed of metal, plastic, composite materials, combinations thereof, or the like without departing from the scope or intent of the present disclosure.

Additionally, as shown in FIGS. 9A and 9B, the blocking frame 100 is immovably secured within the cargo compartment by mounting plates 231. The mounting plates 231 shown may be affixed to the floor 12 by known means, such as mechanical fasteners including bolts, nuts, rivets, screws, interference fittings, and the like, and/or thermal or chemical fastening means such as welding, braising, glues, or the like. In some examples, the mounting plates 231 may extend only to an area immediately surrounding the front and/or rear frame portion 102, rear frame portion 104, or the like. In other examples, the mounting plates 231 may extend for substantially an entire width of the blocking frame 100 thereby interconnecting the sides of the blocking frame 100. In some examples, the mounting plates 231 may include pre-formed apertures or mounting points that are located at positions where preexisting mounting points may be found within the cargo compartment of the motor vehicle. In other examples, the mounting plates 231 may be affixed to newly-formed mounting points within the cargo compartment, such as newly-drilled holes in the cargo compartment, or the like. In some examples, the mounting plates 231 are formed with beveled edges to facilitate and decrease user effort in moving the first and second container sections 16, 18 into and out of the cargo compartment and blocking frame 100. The beveled edges may stretch for the full width of the mounting plates 231 and/or for only a portion thereof.

In further aspects, the interlocking frame segments 107 may be affixed to one another by connector plates 233. The connector plates 233, like the interlocking frame segments 107 of the front and rear frame portions 102, 104, and longitudinal bars 106 may be formed of any of a variety of materials including but not limited to: metals, alloys, plastics, vinyls, composite materials, and the like. In several aspects, the longitudinal bars 106 of the blocking frame are formed of reinforced plates. More specifically, the longitudinal bars 106 shown in FIG. 9B are made of corrugated material having a substantially flat or planar portion, to which a reinforcing plate is attached. The reinforcing plate is formed of similar material to that from which the substantially flat or planar portion is made. The reinforcing plate is rigidly affixed to or otherwise formed unitarily with the substantially flat or planar portion. The resulting longitudinal bars 106' offer packaging advantages in that the corrugated material has a laterally narrow cross-sectional width by comparison with round, rectangular, or other such shapes of longitudinal bar 106 material. The corrugated longitudinal bars 106' also offer relatively light weight, rigid structure, and the like, each of which is at least comparable to the structural advantages offered by longitudinal bars 106 having other cross-sectional shapes.

The connector plates 233 are substantially planar and provide rigid connecting means for the interlocking frame segments 107. Because the connector plates 233 are substantially planar, the blocking frame 100 may be placed extremely closely to the physical structure of the cargo compartment of the vehicle itself. Accordingly, the blocking frame 100 utilizing connector plates 233 does not intrude substantially into the cargo space within the cargo compartment and maximizes the potential size of the first and second container sections 16, 18 which may be held within the blocking frame 100. In some examples, the connector plates 233 define attachment points for vehicle-to-blocking frame 100 connections. Specifically, as shown in FIG. 9B a vehicle attachment 235 is disposed on the blocking frame 100. The vehicle attachment 235 is a spacer rigidly affixed to the blocking frame 100 as well as to an interior surface of the vehicle cargo compartment. That is, the vehicle attachment 235 may have a variety of different shapes and sizes, depending on the particular vehicle cargo compartment into which the blocking frame 100 is mounted. The vehicle attachment 235 should be understood to be easily mountable to the connector plates 233 of the blocking frame 100, or to other portions of the blocking frame 100 without departing from the scope or intent of the present disclosure. In some examples, the vehicle attachment 235 is formed of a structurally rigid rectangular prismatic box-section or similar bar stock material with mounting points such as threaded apertures or the like cut into or otherwise formed into the vehicle attachment 235. In some examples, one or more bushings 236 including rigid, solid, and/or flexible bushings are disposed in some or all of the mounting points of the vehicle attachment 235. The bushings assist users in locating the vehicle attachment 235 to the blocking frame 100 as well as guiding users in attaching the blocking frame 100 to the motor vehicle cargo compartment. Through use of the vehicle attachment 235, the blocking frame 100 may be rigidly mounted within any of a variety of vehicle cargo compartments, thereby reinforcing the blocking frame 100 and locating the blocking frame 100 at a specific location within the cargo compartment.

In some examples the blocking frame 100 is formed of multiple preassembled modular component sections. The multiple preassembled modular component sections may be interchangeable side-to-side and/or end-to-end. In FIG. 9B, for example, the blocking frame 100 includes a frame connector 237, upper frame sections 239, and lower frame sections 241. Each of the upper frame sections 239 shown defines a ladder-like construction composed of multiple interlocking frame segments 107 joined together by known means such as mechanical fasteners including bolts, nuts, rivets, screws, interference fittings, and the like, and/or thermal or chemical fastening means such as welding, braising, glues, or the like. Similarly, the lower frame sections 241 define ladder-like constructions composed of interlocking frame segments 107 joined by means such as those described hereinabove.

The upper and lower frame sections 239, 241 and the frame connector 237 may be provided to a user in a preassembled state, or in component parts, depending on the particular use application. In some examples, the interlocking frame segments 107 of the upper frame sections 239 have a smaller cross-sectional size than the cross-sectional size of the interlocking frame segments of the lower frame sections 241. Accordingly, the upper frame sections 239 and lower frame sections 241 may be assembled with one another via slip-fit attachments, interlocking or interference fit arrangements, or the like. In some examples, one or more

portions of the upper frame sections 239 fit into and are retained within corresponding portions of the lower frame sections 241. The upper and lower frame sections 239, 241 may be permanently or temporarily assembled by use of known attachment means such as mechanical fasteners including bolts, nuts, rivets, screws, interference fittings, and the like, and/or thermal or chemical fastening means such as welding, braising, glues, or the like. Similarly, the frame connector 237 is formed of material having substantially the same or similar cross-sectional sizing as that of the lower frame sections 241. Accordingly, the frame connector 237 fits over and engages with one or more portions of the upper frame sections 239, thereby stabilizing and increasing the rigidity of the blocking frame 100. The frame connector 237 may be permanently or temporarily assembled to the upper frame sections 239 by use of known attachment means such as mechanical fasteners including bolts, nuts, rivets, screws, interference fittings, and the like, and/or thermal or chemical fastening means such as welding, braising, glues, or the like. It should further be appreciated that while the upper and lower frame sections 239, 241 have been described as having ladder-like constructions, variations which depart from ladder-like arrangements are intended to be within the scope of the present disclosure.

Turning now to FIGS. 10A and 10B, the brake mechanism 220 is shown in further detail. The brake pedal 222 may be made via known means such as injection molding, lost foam molding, welding of multiple component parts, or the like. In several aspects, the brake pedal 222 has a pedal surface 232 which is generally oriented upwards, while the brake pad 226 is generally oriented downwards, i.e. toward the floor 12 of the cargo compartment of a vehicle, or towards a floor 12 of a warehouse, or the like. The brake pad 226 is preferably formed of a non-slip or non-skid material such as a rubber, or other such material having a relatively high coefficient of static friction. Accordingly, when the brake pad 226 is engaged with the floor 12, the brake pad 226 prevents horizontal movement of the first and second container sections 16, 18.

The brake pedal 222 is mountable to the brake pivot shaft 224 in a limited number of orientations. For example, and as shown in FIG. 10, the ends 234 of the brake pivot shaft 224 are keyed such that rather than being substantially cylindrical in cross-sectional shape, the ends 234 of the brake pivot shaft 224 have flattened areas 236. The flattened areas 236 interact with corresponding flattened portions 238 of a receiving aperture 240 formed through the brake pedal 222. Thus, the brake pedal 222 may only be mounted on the ends 234 of the brake pivot shaft 224 in predefined orientations. Additionally, the flattened areas 236 and flattened portions 238 ensure that the brake pedal 222 cannot rotate independently of the brake pivot shaft 224 when the brake pedal 222 is engaged with the brake pivot shaft 224.

The actuator rod 228 is substantially cylindrical in shape and extends from the brake pedal 222 to the brake pad 226. More specifically, the actuator rod 228 is attached to the brake pedal 226 by a rod pin 241 which is disposed within a rod pin receiving aperture 242 formed through a portion of the brake pedal 222. The rod pin receiving aperture 242 defines an elongate hole formed through the brake pedal 222 at a location offset from the brake pivot shaft 224. More accurately, the brake pedal 222 includes multiple rod pin receiving apertures 242 disposed on opposite sides of the receiving aperture 240 for the brake pivot shaft 224. The brake pedal 222 is formed in this manner so that the same brake pedal 222 may be used in either left or right-handed applications. That is, the brake pedal 222 may be used in an

arrangement as shown where the actuator rod 228 and brake pad 226 are disposed laterally to the right of the brake pivot shaft 224, or in an arrangement where the actuator rod 228 and brake pad 226 are disposed to the left of the brake pivot shaft 224. Accordingly, production costs can be saved by utilizing a single brake pedal 222 part in all applications. Likewise, the identical actuator rod 228, sleeve 230, and brake pad 226 may be used in either left or right-handed applications by the mere substitution of a differently constructed mounting plate 244.

The actuator rod 228 is slidably disposed within sleeve 230, which is sized and shaped to closely fit around and minimize non-axial movement of the actuator rod 228. That is, the sleeve 230 prevents wobble, or other such lateral movement of the actuator rod 228 as the brake pedal 222 is actuated. The sleeve 230 is fixedly attached to the base portion 48 via one or more mounting plates 244. The mounting plates 244 may be formed of any of a variety of materials including but not limited to: metals, alloys, plastics, vinyls, composite materials, and the like. In the example shown in the figures, the mounting plates 244 are mounted to the bottom surface 63 of the base portion 48 and provide structure to which the casters 61 may attach to the base portion 48. The base portion 48 may further be provided with one or more indentations or siting structures (not specifically shown) which are shaped to accept automated or manual movement means such as robotic arms, lifts, trolleys or the like. In some examples, the indentations or siting structures are formed integrally in the bottom surface 63 of the base portion 48. In other examples, the indentations or siting structures may further include attachment means, keyways, or the like, to further assist in guiding the automated or manual movement means to predefined positions optimally sited to engage with and allow movement of the first and/or second container sections 16, 18.

Referring once more to the mounting plates 244, the mounting plates 244 define substantially planar plate portions 246 extending substantially parallel to the floor 12, and a curved plate portion 248 sized and shaped to nest against curved portions of the bottom surface 63 of the base portion 48. The mounting plates 244 further include vertical planar plate portions 250 which are affixed to vertical portions of the front and rear ends 42, 42' and 40, 40' of the container sections 16, 18. That is, the vertical planar plate portions 250 abut and firmly brace against the front and rear ends 42, 42' and 40, 40' of the container sections 16, 18. The vertical plate portions 250 are fixedly attached to the substantially planar plate portions 246 by any known means, such as mechanical fasteners including bolts, nuts, rivets, screws, press-fit fasteners, clasps, interference fittings, or the like.

Because the sleeve 230 restricts non-axial movement of the actuator rod 228, in order for the brake pedal 222 to engage the brake pad 226 with the floor 12 without tilting or otherwise moving the actuator rod 228 in a non-axial direction, the rod pins 240 slide within the rod pin receiving apertures 242 formed through the brake pedal 222 as the brake pedal 222 is actuated. Additionally, in order to prevent accidental release of the brake mechanism 220, a spring-loaded retainer 252 is provided.

The spring loaded retainer 252 is affixed to one or more of the mounting plates 244 and defines a rod-shaped element 254 and a retainer spring 256. The rod-shaped element 254 extends from the mounting plates 244 and orthogonally through an orifice 258 formed through a portion of the sleeve 230. The actuator rod 228 further includes a detent 260 defined as a depression, scooped-out portion, or the like. The detent 260 defines a portion of the actuator rod 228 having

a reduced cross section relative to the rest of the actuator rod 228, and is oriented such that when the brake pad 226 is in contact with the floor 12, the detent 260 is aligned with the orifice 258 in the sleeve 230. The retainer spring 256 biases an end 257 of the rod-shaped element 254 outwardly away from the mounting plates 244 and towards the orifice 258 within the sleeve 230. Accordingly, when the brake pad 226 is in contact with the floor 12 and the brake pedal 222 is in a locked position, the end 257 of the rod-shaped element 254 is pushed via the retainer spring 256 through the orifice 258 and into the detent 260 in the actuator rod 228, thereby locking the brake mechanism 220 in place in a locked or engaged position such that the brake pad 226 is retained against the floor 12. It should be appreciated that the brake pedal 222 is intended to be manipulated by a person's foot, or the like, thus the spring-loaded retainer 252 provides sufficient locking force to prevent accidental actuation of the brake pedal 222 away from the locked position but may easily be intentionally disengaged by application of sufficient vertical force to a portion of brake pedal 222 opposite the actuator rod 228.

While only a single brake mechanism 220 is shown in each of FIGS. 9, 10A, and 10B, it should be appreciated that the brake mechanism 220 may be present at only one end of each of the first and second container sections 16, 18, or at both ends. That is, it should be appreciated that the brake pivot shaft 224 extends through each of the first and second container sections 16, 18 and may have an identical set of brake mechanism 220 components disposed at and actuatable from each end of the first and second container sections 16, 18.

Turning now to FIGS. 11A, 11B, and 11C and with continued reference to FIGS. 1-10B, a portion of one of the first and/or second container sections 16, 18 and the blocking frame 100 is shown in further detail. In several aspects, the blocking frame 100 includes latch mechanism 262. The latch mechanism 262 consists, broadly, of a spring latch 264, a latch receiver 266, and a retaining hook 268. In several aspects, the latch receiver 266 is affixed to or formed as a part of the structural frame 200 of each of the first and second container sections 16, 18. By contrast, the spring latch 264 is affixed to, formed with, or otherwise attached to the blocking frame 100. The spring latch 264 and latch receiver 266 are disposed at a height "H1" above the floor 12 so that the spring latch 264 extends into and engages with the latch receiver 266 when the first and/or second container sections 16, 18 are disposed maximally outwards and against the blocking frame 100.

The spring latch 264 consists primarily of a latch mount 270, a latch tongue 272, and a latch handle 274 which is attached to the latch tongue 272 by a latch rod 275. In several aspects, the latch mount 270 is a box-like structure attached to or formed directly with a portion of the blocking frame 100. The latch mount 270 defines a cavity through which the latch tongue 272 can at least partially linearly reciprocate. Additionally, the latch tongue 272 is biased towards a front of the cargo compartment and away from the latch mount 270 by a latch spring 276. The latch spring 276 may be any known variety of spring or spring equivalent, including but not limited to: mechanical, electrical, magnetic, electromagnetic, electromechanical, electrohydraulic, electropneumatic, hydraulic, or pneumatic devices capable of producing a spring-force that biases the latch mount 270 as described above. The latch handle 274 is sized and shaped to be manually manipulated by a person or machine. Accordingly, while the latch handle 274 shown in FIGS. 11A and 11B defines a "T-handle", it should be appreciated that any

other shape of latch handle 274 may be used without departing from the scope or intent of the present disclosure. In a further example, the latch handle 274 shown in FIG. 11C extends orthogonally from the latch rod 275. The latch handle 274 of FIG. 11C extends through an aperture or slot 277 formed in a longitudinal portion of the latch mount 270. The latch handle 274 shown in FIG. 11C extends laterally towards a centerline of the cargo compartment. However, it should be appreciated that the latch handle 274 may be oriented in other directions, such as protruding through a longitudinally-extending slot 277 formed in a top surface of the latch mount 270 a bottom surface of the latch mount 270, or the like without departing from the scope or intent of the present disclosure. The latch handle 274 provides a means by which the latch tongue 272 may be retracted against the latch spring 276 and at least partially into the latch mount 270. In additional examples, the latch handle 274 may define a button, or other push and/or pull device capable of transmitting either mechanical motion or electrical or magnetic signals to the latch tongue 272 via the latch spring 276 and latch rod 275, thereby causing the latch tongue 272 to be retracted at least partially into the latch mount 270 when activated by a user or machine.

The latch receiver 266 defines structurally rigid portion of the structural frame 200 of each of the first and second container sections 16, 18. More specifically, the latch receiver 266 is a partial box section formed of structural material such as metals, alloys, plastics, vinyls, composite materials, or the like. The partial box section is defined by at least one curved portion 278 that faces inward relative to the exterior of the structural frame 200 and a flat portion 280. The curved portion 278 reduces or substantially eliminates any potential for interference with or damage to cargo stored within the first and second container sections 16, 18. That is, the curved portion 278 is sized and shaped to protrude as little as possible into the storage volume of each of the first and second container sections 16, 18. The flat portion 280 abuts the curved portion 278 and in some examples is formed by a portion of the vertical portions 204, 204' of the structural frame 200.

Turning specifically to FIG. 11C, and with continuing reference to FIGS. 1-11B, the blocking frame 100 is shown in further detail proximate the spring latch 264. In some examples, the blocking frame 100 may be constructed such that one or more of the interlocking frame segments 107 is connected at an angle "A" to the other interlocking frame segments 107. That is, the interlocking frame segment 107 to which the spring latch 264 is affixed is mounted at an angle "A" other than precisely perpendicular or precisely parallel to the other interlocking frame segments 107 of the blocking frame 100. In examples in which the spring latch 264 is affixed to an interlocking frame segment 107 that is rotated at an angle "A" other than perpendicular or parallel to other interlocking frame segments 107 of the blocking frame 100, the blocking frame 100 provides rotational clearance for the first and second container sections 16, 18 as the first and second container sections 16, 18 are maneuvered within and locked to the blocking frame 100. In several examples, the interlocking frame segment 107 to which the spring latch 264 is mounted may be rotated by between about 0° and about 45° in relation to the other interlocking frame segments 107; or between about 5° and about 30° relative to the other interlocking frame segments 107; or at about 15° relative to the other interlocking frame segments 107. In the example shown in FIG. 11C, the angle "A" of rotation is about 15° relative to the other interlocking frame segments 107. Furthermore, as shown in FIG. 11C,

one or more portions of the blocking frame 100 include angled interlocking frame segments 107' which are shaped and sized to accommodate the rotated interlocking frame segments 107 discussed above.

Referring now to FIGS. 12A and 12B, and with continuing reference to FIGS. 1-11C, the outer vertical members 204' of the structural frame 200 have a cross sectional shape adapted to allow the structural frame 200 to be maneuvered freely into and out of the blocking frame 100 when the latch mechanism 262 is disengaged. More specifically, the outer vertical members 204' have a cross sectional shape that is substantially a box section with a beveled corner 282. The beveled corner 282 allows some rotational movement of the outer vertical members 204' within the retaining hook 268 and/or within or relative to the latch mechanism 262. In several aspects, the first and/or second container sections 16, 18 may be moved into the cargo compartment as described below.

First, one of the first and/or second container sections 16, 18 is rolled in a longitudinal direction through the narrow door frame 110 and into the vehicle cargo compartment. The first and/or second container section 16, 18 is then maneuvered to the appropriate side of the cargo compartment within the blocking frame 100. That is, the open side 24 of the first container section 16 and the open side 24' of the second container section 18 are intended to face inwards towards a centerline of the cargo compartment when the first and second container sections 16, 18 are in place in the blocking frame 100. More specifically, the front end 42 of the first container section 16 is rotated slightly and pushed forward towards the front frame portion 102 where the vertical portion 204' disposed at the outer front portion of the structural frame 200 is received by the retaining hook 268.

Like the latch mount 270, the retaining hook 268 is a structurally-rigid component rigidly affixed to, formed with, or otherwise attached to the blocking frame 100. The retaining hook 268 is sized and shaped to fit around and accept the vertical portion 204' such that the vertical portion 204' cannot move laterally inward or outward when the structural frame 200 and the blocking frame 100 are parallel to one another. However, the retaining hook 268 does allow rotation of the vertical portion 204' so that the structural frame 200 of each of the first and second container sections 16, 18 may be rotated and subsequently moved into and/or out of the cargo compartment. Once the retaining hook 268 at least partially receives the vertical portion 204' as described above, the first container section 16 may be rotated towards and eventually up against and parallel to the blocking frame 100. As the first container section 16 is rotated towards the blocking frame 100, the vertical portion 204' disposed at the outer rear portion of the structural frame 200 encounters the latch tongue 272. As the first container section 16 is rotated past the point at which the vertical portion 204' encounters the latch tongue 272, the latch tongue 272 is forced against the latch spring 276 and away from the vertical portion 204'. Once the vertical portion 204' has passed by the latch tongue 272 and the latch tongue 272 is no longer in physical contact with the vertical portion 204', the latch spring 276 pushes the latch tongue 272 inwards and into the latch receiver 266 thereby retaining the first container section 16 in place against the blocking frame 100. Accordingly, when the latch tongue 272 is engaged in the latch receiver 266 and the retaining hook 268 is engaged with and retaining the vertical portion 204' at the outer front of the first container section 16, the first container section 16 is immovably secured in place against the blocking frame 100.

In order to remove the structural frame 200 of either the first or second container sections 16, 18 from their respective immovably secured positions against the blocking frame 100, the latch handle 274 may be grasped by a user and pulled outwardly, i.e. toward a back of the cargo compartment or a back of the vehicle, thereby overcoming the latch spring 276 and retracting the latch tongue 272 from the latch receiver 266 and into the latch mount 270. Once the latch tongue 272 has been so retracted from the latch receiver 266, the structural frame 200 may be rotated away from the blocking frame 100 and then withdrawn from the retaining hook 268 in substantially the reverse of the process to insert the structural frame 200 in the blocking frame 100 as described hereinabove.

While the above description of the latch mechanism 262, retaining hook 268 and the like has been made with reference to the first container section 16, it should be appreciated that the same procedure and structures may be used with the second container section 18 on the opposite side of the blocking frame 100 from the first container section 16, or with additional blocking frames 100, structural frames 200 and the like without departing from the scope or intent of the present disclosure.

Turning now to FIG. 13, and with continuing reference to FIGS. 1-12B, an enlarged partial cross-sectional view of a portion of the blocking frame 100 and a portion of the structural frame 200 is shown in further detail. In particular, FIG. 13 depicts one of the longitudinal bars 106 of the blocking frame 100. The longitudinal bar 106 of the blocking frame may take a variety of forms, but in the example shown has a substantially rectilinear cross section. FIG. 13 also depicts one of the longitudinal members 212 of the structural frame 200. In some aspects, the longitudinal member 212 may be one of the longitudinal structural members 218' which faces away from the centerline of the cargo compartment when the structural frame 200 is stored fully within the blocking frame 100. In several aspects, the longitudinal member 212 of the structural frame 200 has a cross sectional shape defining a "C" or "U"-shaped channel sized and shaped to engage with and fit closely around the longitudinal bar 106 of the blocking frame 100. The "C" or "U"-shaped cross-sectional shape of the longitudinal member 212 provides rigid structure to the structural frame 200 as well as to the shelves 62 defined therein while also allowing the structural frame 200 to nest tightly against the blocking frame 100, thereby maximizing storage space within each of the first and second container sections 16, 18.

Turning now to FIG. 14, and with continuing reference to FIGS. 1-13, a further example of the blocking frame 100 is shown. The blocking frame 100 of some examples may be equipped with one or more overhead shelves 284. The overhead shelves 284 may be made of any of a variety of materials including metal, metal alloys, plastic, or the like. In some examples, the overhead shelves 284 may be vacuum formed, 3D printed, molded, sand-cast, lost-foam molded, welded or otherwise constructed from multiple separate parts, or the like. The overhead shelves 284 are attached to the blocking frame 100 any of a wide variety of known means including but not limited to: mechanical fasteners such as bolts, nuts, rivets, screws, interference fittings, and the like, and/or thermal or chemical fastening means such as welding, braising, glues, or the like. The overhead shelves 284 may be selectively removable or separable from the blocking frame 100 or integrally formed therewith.

Turning now to FIGS. 15 and 16A-16C and with continuing reference to FIGS. 1-14, an example of the modular portable storage container system 10 is shown in further

detail. In the examples of FIG. 15, the enclosing material 219 may enclose only a portion of the first and second container sections 16, 18 so that each of the first and second container sections 16, 18 has an open top aspect. In an example, the base portion 48 may be formed of enclosing material 219 extending in a substantially planar fashion between bottom member 208 and parallel to the shelves 62 of the first and second container sections 16, 18.

Further, the example of FIGS. 15 and 16A-16C includes an engagement indicator system 300. The engagement indicator system 300 includes one or more position sensors 302, and one or more position indicators 304 in communication with the one or more position sensors 302. The position sensors 302 may include any of a variety of different position-detecting devices such as: electrical switches, mechanical switches, electromechanical switches, optical sensors or switches, pneumatic switches, hydraulic switches, plunger switches, magnetic switches or sensors, such as Hall-effect sensors, or the like. In several aspects, the position sensors 302 are affixed to one or more of the longitudinal bars 106, 106' and/or one or more of the front and/or rear frame portions 102, 104 of the blocking frame 100. The position sensors 302 are positioned to face towards the center of the cargo compartment of the vehicle towards the first and second container sections 16, 18. As the first and second container sections 16, 18 are locked into the blocking frame 100, the first and second container sections 16, 18 come into a sensing proximity of the position sensors 302 and cause the position sensors 302 to send a first signal to the one or more position indicators 304, where the first signal is a latched signal.

In several aspects, the one or more position indicators 304 have at least two operational modes: a first mode in which the position indicators 304 generate a "disengaged" indication, and a second mode in which the position indicators 304 generate an "engaged" indication. In the example shown in FIG. 15, the position indicators 304 include a multiple illuminatable lights, including a disengaged light 306, and an engaged light 308. In one example, the disengaged light 306 and the engaged light 308 operate in a binary fashion. That is, the position sensors 302 generate a second, or unlatched signal and send the unlatched signal to the position indicators 304 and only the disengaged light 306 is illuminated whenever the position sensors 302 are not within sensing proximity of the first and second container sections 16, 18. By contrast, only the engaged light 308 is illuminated when the position sensors 302 are within sensing proximity of the first and second container sections 16, 18. In further examples, the position indicators 304 may operate in a non-binary manner as well. That is, the position indicators 304 may have additional operational modes which notify users that the first and second container sections 16, 18 are partially engaged with and/or partially latched to the blocking frame 100.

The position sensors 302 and position indicators 304 are operated by known means. In electrical, magnetic, or electro-mechanical examples, the position sensors 302 and position indicators 304 may be powered by known electrical power sources or means such as batteries, generators, an electrical system of the vehicle, or the like without departing from the scope or intent of the present disclosure. In several aspects, the electrical means may be disposed on the blocking frame 100, the vehicle, the cargo compartment of the vehicle, the first and second container sections 16, 18, or any combination thereof. The position sensors 302 and/or position indicators 304 may be retrofitted to the blocking frame 100 as shown. In several aspects, the position sensor 302

may be connected via conduits or wires 310 directly to other position sensors 302 and the position indicators 304 of the engagement indicator system 300. While in the foregoing, the position sensors 302 and the position indicators 304 have been described primarily as electrically-active devices, it should be appreciated that purely mechanical, pneumatic, hydraulic, or other such position sensors 302 and position indicators 304 may be used without departing from the scope of the present disclosure. That is, the position sensors 302 may also communicate physically with the position indicators 304 rather than purely electrically. Additionally, while the position indicators 304 have been described as lights, it should be appreciated that the position indicators 304 may include mechanically, pneumatically, hydraulically, or other similarly-activated flag mechanisms, and/or any other visual, tactile, or audible indications that selectively provide an engaged indication and a disengaged indication depending on whether or not the first and second container sections 16, 18 are fully engaged with and locked or latched fully into the blocking frame 100. In several examples, the position indicators 304 may include mechanical flags, lights, speakers, or the like without departing from the scope or intent of the present disclosure.

Turning now to FIGS. 17, 18A, 18B, 19A, and 19B and with continuing reference to FIGS. 1-16C, an example of the modular portable storage container system 10 is shown in further detail. In the example of FIG. 17, each of the retaining hook 268 and the latch mount 270 includes a mounting flange 400 which may be used to attach the spring latch 264 to the blocking frame 100, or to a vehicle cargo compartment as previously described. In further examples, the mounting flange 400 may be used to attach the spring latch 264 and/or the retaining hook 268 to any of a wide variety of infrastructure substrates directly, or indirectly. In some examples, the mounting flanges 400 may attach one or more of the spring latch 264 and the retaining hook 268 to stakes of a stake truck (not specifically shown). More specifically, a U-shaped clamp or the like may partially surround stakes of a stake truck, and fixedly interact with the mounting flanges 400 to secure the spring latch 264 and/or the retaining hook 268 to the stakes of a stake truck. In several non-limiting examples, the infrastructure substrates may include walls and floors of buildings or of vehicles or vehicle cargo compartments. Other examples of infrastructure substrates may include stakes of a stake truck, an interior or exterior wall of a semi or semi tractor trailer, a wall or other such interior surface of an aircraft, a watercraft such as a ship, a train or train car, and/or interior and/or exterior walls, doors, ceiling, and floor of shipping containers and shipping crates. In further non-limiting examples, the latch receiver 266 may define a structurally rigid portion of the structural frame 200 of each of the first and second container sections 16, 18. The structurally rigid portion of the structural frame 200 may include vertical members 204, outer vertical members 204', longitudinal structural members 218, 218'.

Likewise, the mounting flanges 400 may attach one or more of the spring latch 264 and retaining hook 268 to mounting points 402 disposed on fixed infrastructure substrates, such as walls of a building or a vehicle cargo compartment, a floor or a building or vehicle, or mounted to, formed integrally with, or formed in a mounting track 404, or the like. The mounting track 404 may be mounted to, formed integrally with, or otherwise affixed to a variety of substrates, including but not limited to walls of a vehicle cargo compartment, a structure such as a wall of a building (not specifically shown), or the like. In further non-limiting

examples, the mounting points 402 may include magnetized, or selectively magnetized features that interact with corresponding magnetized, selectively magnetized, or otherwise magnetic features of the mounting flanges 400 to secure the mounting flanges 400 in place against the mounting points 402 and/or the mounting track 404. The mounting track 404 may be specially designed for mounting the spring latch 264 and/or retaining hook 268 in some examples. In other examples, the mounting track 404 is an industry standard size and shape, commonly used in the interiors of semi tractor trailers, such as an "E track" tie-down rail, an L-track, a flanged airline-style track, or the like. In some specific non-limiting examples, the mounting points 402 formed in the mounting track 404 define slot-like apertures having transverse length of 2.45 inches, and a width of 0.58 inches.

As shown in FIGS. 17, 18A, 18B, 19A, and 19B, the mounting track 404 includes a series of track mounting features 406. The track mounting features 406 may include mechanical fasteners including bolts, nuts, rivets, screws, interference fittings, and the like, and/or thermal or chemical fastening means such as welding, braising, glues, or the like. In the example shown in the figures, the track mounting features 406 include a plurality of apertures formed through a portion of the mounting track 404 and shaped and sized to accommodate track fasteners (not specifically shown), such as the aforementioned bolts, nuts, rivets, screws, and the like. In several aspects, the mounting features 402 of the mounting track 404 define a series of slot-like apertures formed through a portion of the mounting track 404 and transverse to a longitudinal aspect of the mounting track 404. The mounting features 402 function as detents that interact with a slide lock 408 shown in further detail in FIGS. 18A and 18B, and in partial cross-section in FIGS. 19A and 19B.

Slide locks 408 are attached to or otherwise formed with each end of the mounting flanges 400 of each of the spring latch 264 and the retaining hook 268. That is, one slide lock 408 is affixed to a latch handle end 410 of the mounting flange 400 of the spring latch 264, and a separate slide lock 408 is affixed to the latch tongue end 412 of the spring latch 264. Similarly, one slide lock 408 is affixed to a distal end 414 of the mounting flange 400 of the retaining hook 268, and another slide lock 408 is affixed to a hook end 416 of the mounting flange 400 of the retaining hook 268. As can be seen in FIGS. 18A and 18B, the latch handle end 410 of the mounting flange 400 of the spring latch 264 and the distal end 414 of the mounting flange 400 of the retaining hook 268 are structurally identical, despite facing in opposite directions when engaged with the mounting track 404. In several aspects, the slide locks 408 are attached to the mounting flanges 400 by lock mounting features 418. In several aspects, the lock mounting features 418 may include mechanical fasteners including bolts, nuts, rivets, screws, interference fittings, and the like, and/or thermal or chemical fastening means such as welding, braising, glues, and the like. The lock mounting features 418 firmly locate and affix the slide lock 408 to the mounting flanges 400.

Turning now more particularly to FIGS. 19A and 19B, and with continuing reference to FIGS. 1-18B, an exemplary slide lock 408 is shown in additional detail in a disengaged position 500 and in an engaged position 502. The slide lock 408 includes a lock housing 510. The lock housing 510 as shown includes the lock mounting features 418 and the lock mounting features are used to affix the lock housing 510 to the mounting flanges 400. The lock housing 510 accepts and contains lock arms 512, and a lock spring 514. While FIGS.

19A and 19B depict two lock arms 512 disposed within the lock housing 510, it should be appreciated that other quantities of lock arms 512 may be used without departing from the scope or intent of the present disclosure. In a non-limiting example, the lock arms 512 have substantially L-shaped profiles and are disposed opposite to and facing away from one another within the lock housing 510. The lock arms 512 engage with the lock housing 510 in both vertical and lateral aspects as will be described in further detail below.

The lock spring 514 engages with the lock arms 512 and biases the lock arms 512 away from one another. The lock spring 514 is depicted as a coil spring, however any other type of spring or spring-like mechanism may be used without departing from the scope or intent of the present disclosure. That is, the lock spring 514 may be a coil spring, wave spring, a leaf spring, a disk spring, a torsion spring, or other such spring which may bias the lock arms 512 away from one another. In further examples, the lock spring 514 may define magnets, electromagnets, or the like, and a magnetic field may selectively bias the lock arms 512 away from one another within the lock housing 510. In electrically or electromagnetically actuated examples, a servo, electromagnet, electrohydraulic, electropneumatic, or other such electromechanical actuator may selectively bias the lock arms 512 away from one another within the lock housing 510, and also be actuated to retract the lock arms 512 towards one another, thereby allowing slidable or retractable movement of the slide lock 408 relative to the mounting points 402.

In several aspects, the lock housing 510 includes at least one lock arm lateral aperture 516 and at least one lock arm vertical aperture 518. The lateral aperture 516 allows the lock arms 512 to move or slide laterally within the lock housing 510, while the vertical aperture(s) 518 define lateral movement limits for vertical portions 520 of the lock arms 512. That is, the vertical apertures 518 limit movement of the lock arms 512 towards a center post 522 aligned with a longitudinal axis of the mounting flange 400, as well as movement outwards and laterally away from the center post 522. It should be appreciated that the slide lock 408 and mounting plate 400 shown in the figures includes lock arms 512 that may selectively move linearly towards and away from the center post 522 in a substantially linear fashion, other types of movement are intended to be captured within the scope of the present disclosure. In some examples, the lock arms 512 may move linearly, rotationally, vertically, and/or horizontally outward from the center post 522, in addition to, or instead of the substantially linear, movement against the spring or magnetic bias shown in the figures, and described herein.

In several aspects, the vertical portions 520 of the lock arms 512 are sized and shaped to extend for a distance upward and out of the vertical apertures 518, so that the vertical portions 520 may be grasped by a human hand, or by a tool shaped and sized to manipulate the vertical portions 520. When grasped by a human hand or tool and manipulated towards the center post 522, the lock arms 512 are retracted towards the center post 522 as shown in FIG. 19A. When all of the slide locks 408 on the mounting flange 400 of the latch mount 270 of the spring latch 264 are simultaneously manipulated to the disengaged position 500, the entire latch mount 270 is slidably movable along the mounting track 404. Similarly, when all of the slide locks 408 on the mounting flange 400 of the retaining hook 268 are simultaneously manipulated to the disengaged position 500, the entire retaining hook 268 is slidably movable along the

mounting track 404. By providing for slidable movement of the spring latch 264 and the retaining hook 268 along the mounting track 404 first and second container sections 16, 18 of varying sizes may be accommodated. That is, by providing for selective slidable movement of the spring latch 264 and retaining hook 268, the latch mechanism 262 is capable of receiving, retaining, and immovably securing first and/or second container sections 16, 18 of dramatically varying lengths in a variety of different applications. Likewise, in examples in which the mounting flanges 400 of the spring latch 264 and/or retaining hook 268 are affixed directly to vehicle cargo compartment surface, a building, or the like, the exact locations of the spring latch 264 and retaining hook 268 may be varied relative to one another to accommodate whatever size first and second container sections 16, 18 are being used.

Each of the lock arms 512 further includes a beveled portion 524 disposed at a laterally outward-extending end of the lock arms 512. The beveled portion 524 allows for the slide lock 408 to be easily and accurately located within the slot-like mounting points 402 formed through the mounting track 404. That is, when rather than requiring that the lock arms 512 be manually or automatically, continuously held against the center post 522 while the slide lock 408 is being moved along the mounting track 404, the lock arms 512 may be released and allowed to extend outwards through the lateral apertures 516 of the slide lock 408 until the slide lock 408 is pressed vertically into and against the mounting track 404 in a position in which the lock arms 512 can engage with the mounting points 402. As the slide lock 408 is pressed vertically against and into the mounting track 404, the beveled portions 524 of the lock arms 512 contact the mounting points 402 formed in the mounting track 404 and are forced inwards and against the bias of the lock spring 514 towards the center post 522 by the mounting points 402, thereby allowing the slide lock 408 to enter the mounting points 402. Once the slide lock 408 has been fully inserted into the mounting points 402, the lock spring 514 causes the lock arms 512 to slide outwards and away from the center post 522, through the lateral apertures 516, and laterally beyond an outer lateral edge 526 of the mounting points 402. When the slide lock 408 has been fully inserted into the mounting points 402 and into the engaged position 502, as shown in FIG. 19B, the lock arms 512 extend beyond the outer lateral edge 526 of the mounting points 402, thereby retaining the slide lock 408, and the mounting plates 400 firmly in position against the mounting point 402 and the mounting track 404.

A lock clip 528 is used to selectively lock the lock arms 512 in the engaged position 502. The lock clip 528 defines a substantially U-shaped profile having clip arms 530 extending from a clip base 532 to clip detents 534. The clip arms 530, clip base 532 and clip detents 534 are sized and shaped to surround and lockingly engage with the center post 522 when the lock clip 528 is in the engaged position 502. The lock clip 528 is formed of a material that has a predefined quantity of flexibility that allows the lock clip 528 to be maneuvered into position about the center post 522. In several aspects, the quantity of flexibility is based on the fact that in order for the clip detents 534 to be selectively engageable with the center post 522, the clip arms 530 have to flex slightly to "open" the U-shaped profile as the lock clip 528 is pressed into engagement from the disengaged position 500 depicted in FIG. 19A to the engaged position 502 depicted in FIG. 19B. In the engaged position 502, the clip detents 534 lockingly engage with a lower edge 536 of the center post 522 to retain the lock clip 528 securely in

position surrounding the center post 522. The lock clip 528 may include manually-manipulatable features (not specifically shown), such as handles, slots for accepting a release tool, apertures which may be used to pry the lock clip 528 upward and into the disengaged position 500 from the engaged position 502.

In several aspects, the lock clip 528 base portion 532 extends for a predetermined clip width 538. The clip width 538 is selected such that when the lock clip 528 is in the engaged position 502, the lock clip 528 contacts the vertical portions 520 of the lock arms 512, and a combined width 540 of the lock clip 528 and the vertical portions 520 of the lock arms 512 is substantially identical to the transverse extent or length of the mounting points 402 formed in the mounting track 404. Accordingly, when the lock clip 528 is in the engaged position 502, the lock arms 512 are prevented from moving towards the center post 522, thereby causing the slide lock 408 to be locked into position on the mounting track 404.

In additional non-limiting examples, when one or more of the first and second container sections 16, 18 is fully engaged and captured within the spring latch 264 and the retaining hook 268, one or more magnets or electromagnets disposed in one or more of the first and second container sections 16, 18, the spring latch 264 and retaining hook 268, and/or the mounting points 402 and/or the mounting track 404 cause the first and second container sections 16, 18 to be securely and immovably fixed in position. More specifically, the magnets prevent wiggle, jostling, rattling, and the like when the first and second container sections 16, 18 are captured within the spring latch 264 and retaining hook 268, thereby reducing a quantity of noise, vibration, and harshness (NVH) perceptible to users of vehicles equipped with the system 10 of the present disclosure.

A modular portable storage container system 10 of the present disclosure offers several advantages. In particular, the modularity of the storage container system 10 allows for use in a wide variety of different industrial, warehouse and private applications with relatively low cost of manufacturing and ease of scaling for different uses. Moreover, the modular portable storage container system 10 improves transit efficiency by providing a means for loading storage containers 14, warehousing the storage containers 14, moving the storage containers 14 into delivery and/or work or private vehicles, opening and securing the storage containers 14 within the cargo compartments of the vehicles with low effort and high portability, thereby increasing work efficiency for system 10 users.

The description of the present disclosure is merely exemplary in nature and variations that do not depart from the gist of the present disclosure are intended to be within the scope of the present disclosure. Such variations are not to be regarded as a departure from the spirit and scope of the present disclosure.

What is claimed is:

1. A modular portable storage container system comprising:
  - a first container section defining a first partial volume of storage space;
  - a second container section defining a second partial volume of storage space, each of the first and second container sections having a structural frame;
  - a latch mechanism selectively retaining the structural frame of each of the first container section and the second container section against an infrastructure substrate, the latch mechanism having:
    - a spring latch;

a latch receiver; and a retaining hook, wherein one of the spring latch and the latch receiver is disposed on mounting points disposed either directly or indirectly on the infrastructure substrate while the other of the spring latch and the latch receiver is disposed on the structural frames of each of the first container section and/or the second container section;

wherein the first and second container sections are movable between at least an unlatched position and a latched position, wherein in the unlatched position, the first and second container sections are freely movable relative to the infrastructure substrate and the mounting points and in the latched position the structural frames of each of the first and second container sections are retained in contact with the mounting points of the infrastructure substrate via the latch mechanism, wherein the spring latch and the latch receiver are disposed opposite one another and engage with one another when the first container section and/or the second container section are in a latched position, and wherein the retaining hook engages with an outer vertical portion of the structural frame to partially rotatably retain the structural frame; and

wherein each of the spring latch and the retaining hook include mounting flanges that are selectively fixedly mountable to the mounting points of the infrastructure substrate in one or more positions defined by a size of the first container section, or a size of the second container section; wherein the system further comprises:

a mounting track affixed to the infrastructure substrate, the mounting track having one or more of the mounting points, the mounting flanges of the spring latch and the retaining hook being selectively, fixedly mountable to the mounting points wherein each of the mounting flanges further includes:

at least one slide lock movable between at least an engaged position and a disengaged position, the slide lock selectively engageable with the mounting points of the mounting track,

wherein when the at least one slide lock is in the disengaged position, the mounting flanges are movable relative to the mounting track; and

when the at least one slide lock is in the engaged position, the mounting flanges are immovably secured to the mounting track.

2. The system of claim 1, wherein the infrastructure substrate comprises at least one of:

walls and floors of buildings; walls and floors of vehicles or vehicle cargo compartments; stakes of a stake truck; an interior or exterior wall of a semi or semi tractor trailer; a wall or interior surface of an aircraft or aircraft fuselage; a wall or interior surface of a watercraft; a wall or interior surface of a train or train car; interior walls, doors, and floors of shipping containers; and interior walls, doors, and floors of shipping crates.

3. The system of claim 1, wherein each of the at least one slide locks further comprises:

a lock housing fixed to the mounting flanges; lock arms movably disposed within the lock housing; a lock spring disposed within the lock housing, and between the lock arms, the lock spring biasing the lock arms away from each other; and

the lock arms lockingly engaging with the mounting points of the mounting track and immobilizing the slide lock relative to the mounting track in the engaged position.

4. The system of claim 3, wherein each of the at least one slide locks further comprises:

a lock clip, the lock clip having clip arms extending from a clip base to clip detents, the clip arms being substantially parallel to one another, and substantially orthogonal to the clip base, the clip detents, clip base, and clip arms sized and shaped to surround and lockingly engage with a center post of the mounting flange, wherein the center post of the mounting flange is located between the lock arms.

5. The system of claim 4, wherein in the disengaged position, the lock arms are movable towards and away from the center post, and

wherein in the engaged position, the lock clip is selectively lockingly engageable with the center post such that the lock clip substantially surrounds the center post and contacts and separates each of the lock arms, thereby preventing the lock arms from moving towards or away from one another and the center post, and wherein the clip detents contact and lockingly engage with a lower edge of the center post to retain the lock clip securely in position surrounding the center post.

6. The system of claim 5, wherein a combined width of the lock clip and vertical portions of the lock arms is substantially identical to a transverse extent or length of the mounting points formed in the mounting track.

7. The system of claim 3, wherein the lock spring further comprises one or more of:

a mechanical spring comprising:
a coil spring, a leaf spring, a wave spring, a torsion spring, and a disk spring; or

an electromagnetic actuator comprising:
a magnet, an electromagnet, a servo, an electrohydraulic, electropneumatic, or electromechanical actuator; or a combination of the mechanical spring and the electromagnetic actuator, wherein the lock spring biases the lock arms away from one another and away from the center post of the mounting flange.

8. A modular portable storage container system comprising:

a first container section defining a first partial volume of storage space;

a second container section defining a second partial volume of storage space, each of the first and second container sections having a structural frame;

a latch mechanism selectively retaining the structural frame of each of the first container section and the second container section against an infrastructure substrate, the latch mechanism having:

a spring latch;

a latch receiver; and

a retaining hook, wherein one of the spring latch and the latch receiver is disposed on mounting points disposed either directly or indirectly on the infrastructure substrate while the other of the spring latch and the latch receiver is disposed on the structural frames of each of the first container section and/or the second container section;

wherein the first and second container sections are movable between at least an unlatched position and a latched position, wherein in the unlatched position, the first and second container sections are freely movable relative to the infrastructure substrate and the mounting

points and in the latched position the structural frames of each of the first and second container sections are retained in contact with the mounting points of the infrastructure substrate via the latch mechanism, wherein the spring latch and the latch receiver are disposed opposite one another and engage with one another when the first container section and/or the second container section are in a latched position, and wherein the retaining hook engages with an outer vertical portion of the structural frame to partially rotatably retain the structural frame;

10 a mounting track affixed to the infrastructure substrate, the mounting track having one or more of the mounting points, the mounting flanges of the spring latch and the retaining hook being selectively, fixedly mountable to the mounting points;

15 at least one slide lock movable between at least an engaged position and a disengaged position, the slide lock selectively engageable with the mounting points of the mounting track;

20 wherein when the at least one slide lock is in the disengaged position, the mounting flanges are movable relative to the mounting track, and when the at least one slide lock is in the engaged position, the mounting flanges are immovably secured to the mounting track; and

25 wherein each of the spring latch and the retaining hook include mounting flanges that are selectively mountable to the mounting points of the mounting track in one or more positions defined by a size of the first container section, or a size of the second container section;

30 wherein each of the at least one slide locks further comprises:

35 a lock housing fixed to the mounting flanges;

lock arms movably disposed within the lock housing;

a lock spring disposed within the lock housing, and between the lock arms, the lock spring biasing the lock arms away from each other; and

40 the lock arms lockingly engaging with the mounting points of the mounting track and immobilizing the slide lock relative to the mounting track in the engaged position.

45 9. The system of claim 8, wherein the infrastructure substrate comprises at least one of:

walls and floors of buildings; walls and floors of vehicles or vehicle cargo compartments; stakes of a stake truck; an interior or exterior wall of a semi or semi tractor trailer; a wall or interior surface of an aircraft or aircraft fuselage; a wall or interior surface of a watercraft; a wall or interior surface of a train or train car; interior walls, doors, and floors of shipping containers; and interior walls, doors, and floors of shipping crates.

50 10. The system of claim 8, wherein each of the at least one slide locks further comprises:

a lock clip, the lock clip having clip arms extending from a clip base to clip detents, the clip arms being substantially parallel to one another, and substantially orthogonal to the clip base, the clip detents, clip base, and clip arms sized and shaped to surround and lockingly engage with a center post of the mounting flange, wherein the center post of the mounting flange is located between the lock arms.

55 11. The system of claim 10, wherein in the disengaged position, the lock arms are movable towards and away from the center post, and

wherein in the engaged position, the lock clip is selectively lockingly engageable with the center post such that the lock clip substantially surrounds the center post and contacts and separates each of the lock arms, thereby preventing the lock arms from moving towards or away from one another and the center post, and wherein the clip detents contact and lockingly engage with a lower edge of the center post to retain the lock clip securely in position surrounding the center post.

10 12. The system of claim 11, wherein a combined width of the lock clip and vertical portions of the lock arms is substantially identical to a transverse extent or length of the mounting points formed in the mounting track.

15 13. The system of claim 8, wherein the lock spring further comprises one or more of:

a mechanical spring comprising:

a coil spring, a leaf spring, a wave spring, a torsion spring, and a disk spring; or

an electromagnetic actuator comprising:

a magnet, an electromagnet, a servo, an electrohydraulic, electropneumatic, or electromechanical actuator; or a combination of the mechanical spring and the electromagnetic actuator, wherein the lock spring biases the lock arms away from one another and away from the center post of the mounting flange.

14. A modular portable storage container system comprising:

a first container section defining a first partial volume of storage space;

a second container section defining a second partial volume of storage space, each of the first and second container sections having a structural frame;

a latch mechanism selectively retaining the structural frame of each of the first container section and the second container section against an infrastructure substrate, the latch mechanism having:

a slide lock;

a latch receiver; and

30 a retaining hook, wherein one of the spring latch and the latch receiver is disposed on mounting points disposed either directly or indirectly on the infrastructure substrate while the other of the spring latch and the latch receiver is disposed on the structural frames of each of the first container section and/or the second container section;

a mounting track affixed to the infrastructure substrate, the mounting track having one or more of the mounting points, the mounting flanges of the spring latch and the retaining hook being selectively, fixedly mountable to the mounting points;

35 at least one slide lock movable between at least an engaged position and a disengaged position, the slide lock selectively engageable with the mounting points of the mounting track, the slide lock comprising:

a lock housing fixed to the mounting flanges; lock arms having substantially L-shaped profiles, the lock arms disposed opposite one another and facing away from one another, the lock arms movably disposed within the lock housing;

40 a lock spring disposed within the lock housing, and between the lock arms, the lock spring biasing the lock arms away from each other;

a lock clip, the lock clip having clip arms extending from a clip base to clip detents, the clip arms being substantially parallel to one another, and substantially orthogonal to the clip base, the clip detents, clip base, and clip arms sized and shaped to surround

39

and lockingly engage with a center post of the mounting flange, wherein the center post of the mounting flange is located between the lock arms; wherein when the at least one slide lock is in the disengaged position, the mounting flanges are movable relative to the mounting track; and when the at least one slide lock is in the engaged position, the mounting flanges are immovably secured to the mounting track by the lock arms lockingly engaging with the mounting points of the mounting track and immobilizing the slide lock relative to the mounting track in the engaged position; wherein the first and second container sections are movable between at least an unlatched position and a latched position, wherein in the unlatched position, the first and second container sections are freely movable relative to the infrastructure substrate and the mounting points and in the latched position the structural frames of each of the first and second container sections are retained in contact with the mounting points of the infrastructure substrate via the latch mechanism, wherein the spring latch and the latch receiver are disposed opposite one another and engage with one another when the first container section and/or the second container section are in a latched position, and wherein the retaining hook engages with a portion of the structural frame to partially rotatably retain the structural frame; and wherein each of the spring latch and the retaining hook include mounting flanges that are selectively mountable to the mounting points of the infrastructure substrate in one or more positions defined by a size of the first container section, or a size of the second container section.

15. The system of claim 14, wherein the infrastructure substrate comprises at least one of: walls and floors of buildings; walls and floors of vehicles or vehicle cargo compartments; stakes of a stake truck; 35

40

an interior or exterior wall of a semi or semi tractor trailer; a wall or interior surface of an aircraft or aircraft fuselage; a wall or interior surface of a watercraft; a wall or interior surface of a train or train car; interior walls, doors, and floors of shipping containers; and interior walls, doors, and floors of shipping crates.

16. The system of claim 15, wherein in the disengaged position, the lock arms are movable towards and away from the center post, and

wherein in the engaged position, the lock clip is selectively lockingly engageable with the center post such that the lock clip substantially surrounds the center post and contacts and separates each of the lock arms, thereby preventing the lock arms from moving towards or away from one another and the center post; wherein the clip detents contact and lockingly engage with a lower edge of the center post to retain the lock clip securely in position surrounding the center post; and

wherein a combined width of the lock clip and vertical portions of the lock arms is substantially identical to a transverse extent or length of the mounting points formed in the mounting track.

17. The system of claim 16, wherein the lock spring further comprises one or more of:

a mechanical spring comprising:
a coil spring, a leaf spring, a wave spring, a torsion spring, and a disk spring; or

an electromagnetic actuator comprising:
a magnet, an electromagnet, a servo, an electrohydraulic, electropneumatic, or electromechanical actuator; or a combination of the mechanical spring and the electromagnetic actuator, wherein the lock spring biases the lock arms away from one another and away from the center post of the mounting flange.
